2,089,904

MACHINE AND METHOD FOR KNITTING
WELTED SPLIT WORK HOSIERY

Robert H. Lawson, Pawtucket, and John Lawson, Bristol, R. I., assignors to Hemphill Company, Central Falls, R. I., a corporation of Massachusetts

Application August 5, 1924, Serial No. 730,164
Renewed August 31, 1934

46 Claims. (Cl. 66—43)

This invention relates to mechanism for and method of knitting welted hosiery and particularly welted split work, and more particularly to automatic circular knitting machines for forming an integral inturned welt upon split work hosiery together with the method of knitting such hosiery and also such hosiery as an article of manufacture.

In order that the principle of the invention may be readily understood, we have in the accompanying drawings disclosed one embodiment of means characterizing the mechanism of the invention and by which the method thereof may be carried out and the fabric of the invention produced.

In the drawings:

Fig. 1 is a side elevation of a lady's stocking knitted in accordance with the invention;

Fig. 1a is a similar view of a series of stockings connected by breaking threads;

Fig. 2 is a similar view of a half-hose or sock similarly knitted;

Fig. 3 is a plan view upon an enlarged scale of a portion of the fabric knitted in accordance with the invention;

Fig. 4 is a front elevation of a circular knitting machine embodying or containing the mechanism of the invention;

Fig. 5 is an end elevation of the mechanism shown in Fig. 4;

Fig. 6 is a rear elevation thereof;

Fig. 7 is a front elevation of the upper part of the mechanism upon an enlarged scale;

Fig. 8 is an end elevation thereof upon an enlarged scale;

Fig. 9 is a plan view of the mechanism shown in Fig. 7;

Fig. 10 is a vertical central section upon the line 10—10 of Fig. 9;

Fig. 11 is a horizontal section upon the line 11—11 of Fig. 10 and showing the sector in position to hold the web against the under face of the dial;

Fig. 12 is a horizontal section upon the line 12—12 of Fig. 7;

Fig. 13 is a side elevation of the dial in position over the cylinder together with the cutter and binder for both threads mounted thereon;

Fig. 14 is a side elevation of the dial swung laterally outward from over the needle head, the latter being shown in vertical section;

Fig. 15 is a detail in side elevation of so-called cam No. 1 pertaining to the welt formation and a portion of the means for operating the same;

Fig. 16 is an inside elevation of said cam No. 1 and also showing the instep cams;

Fig. 17 is a side elevation of so-called cam No. 2 also pertaining to the welt formation and a portion of its operating means;

Fig. 18 is an inside elevation of said cam No. 2;

Fig. 19 is an inside elevation of so-called cam No. 3, also pertaining to the welt formation;

Fig. 20 is a side elevation of said No. 3 cam and a portion of its operating means;

Fig. 21 is a plan view of the drum and the operating levers controlled thereby, the frame appearing in section;

Figs. 22 to 26, inclusive, and Fig. 28, are side elevations of six cams upon the auxiliary drum pertaining to the welt formation and indicating the levers or parts controlled thereby;

Fig. 27 is a side elevation of the ratchet upon the end of the auxiliary drum;

Fig. 29 is a perspective view of the auxiliary drum and the connections therefrom to the various cams, but not drawn to exact scale;

Fig. 30 is a plan view of the dial with the cams thereof shown in dotted position, the jacks being retracted;

Fig. 31 is a vertical section thereof upon the line 31—31 of Fig. 30;

Fig. 32 is a plan view of the dial with the jacks projecting for welting;

Fig. 33 is a vertical section of Fig. 32 on the line 33—33 of said figure;

Fig. 34 is a plan of the dial with the jacks positioned for unloading, that is, for the transfer of the loops back to the needles at the end of the formation of the welt;

Fig. 35 is a vertical section of the dial on the line 35—35 of Fig. 34;

Fig. 36 is an inside elevation showing the position of the two sets of knitting cams and certain other cams, needles and jacks at the end of the toe and the insertion of the breaking thread, being position No. 1;

Fig. 37 is a perspective view of certain of the jacks and needles appearing in Fig. 36;

Fig. 38 is a view similar to Fig. 36 but indicating the parts in position No. 2;

Fig. 39 is a perspective view similar to Fig. 37, but representing certain jacks and needles in position No. 2;

Figs. 40 and 41 are views similar to Figs. 36 and 37 but representing the parts in position No. 3;

Figs. 42 and 43 are views similar to Figs. 36 and 37 but representing the parts in position No. 4;

Figs. 44 and 45 are views similar to Figs. 36 and 37 but representing the parts in position No. 5;

Figs. 46 and 47 are views similar to Figs. 36 and 37, but representing the parts in position No. 6;

Fig. 48 is a side elevation of the first elevated or alternate needles as elevated for the loading of the jacks in a first course;

Fig. 49 is a view of two needles and an associated transfer jack in side elevation in one position of operation;

Fig. 50 is a view similar to Fig. 48, but representing the remaining needles as elevated for the loading of the jacks in the succeeding course and representing said jacks as loaded;

Fig. 51 is a view similar to Fig. 47, but representing a needle and jack of the said remaining needles in elevated position;

Fig. 52 is a diagram in inside elevation of the various cams for actuating the needles, said cams occupying their proper position for circular knitting, the needles moving in a counterclockwise direction;

Fig. 53 is a diagrammatic view similar to Fig. 52 illustrating the various cams in position preparatory to knitting either the heel or the toe pocket of the stocking, the needles moving in a clockwise direction;

Fig. 54 is a diagrammatic view similar to Fig. 52 but representing the cams as arranged for knitting the split fabric of the foot or of the ankle and with the cylinder moving in a forward or counterclockwise direction;

Fig. 55 is a diagram similar to Fig. 54, but with the cylinder moving in a reverse or clockwise direction;

Fig. 56 is a side elevation of one of the transfer instruments;

Fig. 57 is an edge view thereof;

Fig. 58 is an elevation of the dial and immediately cooperating parts viewing the same at a position ninety degrees from that shown in Fig. 14;

Fig. 59 is a similar view of the dial and immediately cooperating parts viewing the same one hundred and eighty degrees from the position shown in Fig. 58;

Fig. 60 is a horizontal section thereof upon the line 60—60 of Fig. 58;

Fig. 61 is a vertical central section thereof taken through the dial and its immediately supporting parts;

Fig. 62 is an edge elevation of a portion of the floating ring;

Fig. 63 is an underneath view of a portion of the said floating ring;

Fig. 64 is a side elevation, somewhat diagrammatic, of the first elevated or alternate needles as elevated for the loading of the jacks, which in number are, in this preferred form of the invention, but one half the number of needles, and represents the jacks as loaded therefrom;

Fig. 65 is a similar view but representing the elevation of the remaining needles and the loading of the jacks therefrom according to such form of the invention;

Figs. 66 and 67 are views similar to Figs. 64 and 65, but representing still another form of the invention;

Figs. 68 and 69 are views similar to Figs. 64 and 65 but representing still another form of the invention;

Figs. 70 and 71 are views similar to Figs. 64

and 65, but representing still another form of the invention;

Fig. 72 is a view similar to Fig. 64, but representing the loading of the jacks in one course, but one half as many jacks being employed as 5 needles;

Fig. 73 is a diagram indicating the appearance of the loops in the first and second courses of the loading, according to that form of the invention diagrammatically illustrated in Figs. 48 and 50; 10

Fig. 74 is a similar diagram representing the appearance of the loops in loading when operating according to the preferred form of the invention indicated in Figs. 64 and 65;

Figs. 75 to 78 inclusive are similar diagrams 15 representing the appearance of the loops in loading according to those forms of the invention shown respectively in Figs. 66 and 67, 68 and 69, 70 and 71, and 72;

Fig. 79 is a plan view of the sinker cap constructed and arranged to cause the dropping off of every stocking and constituting a modification of the invention;

Fig. 80 is a side elevation thereof;

Fig. 81 is a detail mainly in side elevation of a portion of the parts shown in Fig. 80, but indicating certain of the parts as broken away;

Fig. 82 is a detail in vertical section upon the line 82—82 of Fig. 79;

Fig. 83 is a detail in vertical section upon the line 83—83 of Fig. 79; and

Fig. 84 is a detail in side elevation looking from the left in Fig. 79.

The mechanism of the invention while in its broadest aspect applicable to the production of numerous fabrics as well as various parts and kinds of hosiery, more particularly relates to means for forming an integral welt—desirably an integral inturned welt—as an integral part of a stocking or hose that is knit by split work either in the foot or in the leg or both, such split work being knitted for any of the purposes for which split work is customarily provided, as, for example, as disclosed in Patent No. 1,458,833, June 12, 1923, but peculiarly cooperating with the formation of the inturned welt, as hereinafter set forth. While the split work may be characterized by suture lines crossing wales of the fabric as disclosed in said patent, we will for simplicity of description describe the invention as applied to the manufacture of split work, the suture lines whereof follow the wales of the fabric instead of crossing the same.

An important feature of the invention involves or relates to the formation of an integral welt 55 desirably of the inturned type, upon hosiery of split work type, and we have coordinated and co-related the elements or parts of the mechanism so that for the first time in the art, so far as we are aware, such hosiery or fabric is produced.

Obviously the invention may be embodied in various different types of circular knitting machines, but we will, without limiting ourselves thereto, disclose the same as embodied in a 65 circular knitting machine of the so-called Banner type and represented as having latch needles. Under suitable conditions, we may employ other types of needles and in such case we would modify the mechanism in such manner as to provide 70 for the transfer of loops from and back to the needles in accordance with the invention. Our disclosure of latch needles only is therefore not a limitation.

We will first describe in necessary detail a 75

circular knitting machine of the latch needle type for producing a stocking having split work and will then disclose the fundamental changes therein and with which the invention is particularly concerned.

The invention may be applied to a knitting machine wherein the needle cylinder rotates and the cam ring is stationary or to a machine wherein the cam ring rotates and the needle cylinder is stationary. We have represented a machine of the former type and having characteristics of the said Banner machine fundamentally disclosed in the U. S. Patent to Hemphill, No. 933,443, September 7, 1909.

Said machine has a frame 1 within which is mounted a needle cylinder 2 preferably, although not necessarily, revoluble and a non-revoluble cam ring or carrier. Mounted in the main frame 1 is the main shaft 5 carrying suitable pulleys 6, 7 8, respectively employed as quick speed, slow speed and loose pulley. A pattern shaft 9 is mounted in said frame and has thereon an appropriate pattern or cam drum 10. Upon said pattern drum is a peripheral rib 25 or cam 11 which engages with a follower 13 carried by a pivoted clutch shifting lever 14 connected with and for throwing the usual clutch from reciprocating to rotary driving instrumentalities, and vice versa, said latter instrumentalities being well known features of said Hemphill patent and for further information concerning which reference may be had thereto.

The follower 13 is adapted to travel through cross slots 12 from one side of the rib 11 to the other so as to effect the shifting of said clutch member. One of such cross slots is shown in Fig. 4.

By means of the mechanism just described the needle cylinder 2 is adapted to be given at certain times in the knitting operation, a continuous rotary movement, as, for example, during the formation of the welt, and the upper part of the leg down to the ankle portion, while at other times the needle cylinder is given a to and fro or reciprocating movement not only during the knitting of the heel and toe pockets of the stocking, but also for the formation of split work during the knitting of the ankle or a portion thereof, and particularly that part which includes the high splice, and also during the knitting of the foot. By such to and fro or reciprocating movement suture seams are formed at opposite sides of the ankle or of the foot or both, and as herein disclosed said seams follow, that is, are parallel with, wales of the fabric, though we may within the scope of the invention cause said suture seams or certain of them, and particularly those at the high splice portion, to cross wales of the fabric so as to provide a tapered high splice, but without the formation of float threads at any time in the knitting operation, thereby entirely avoiding all complication of parts and operations arising out of the manipulation of float threads at the lower side of the dial or support for the transfer instruments that participate in the formation of the welt.

While within the scope of the invention the knitting of the stocking may commence at the upper end of the leg or at the toe, we prefer the former order of procedure, and without limiting the invention thereto will describe the stocking as knitted in such manner.

The cam plate 3 desirably has provision for a limited vertical movement and to that end is mounted upon the usual cam slide 15 itself

mounted for vertical movement in the frame 1 and carrying at its lower end cam followers 16, 17, 18 adapted to engage ribs upon a cam 19 mounted upon and adapted to turn with the pattern shaft 9, said cam 19 being adapted to move said cam plate 3 up or down to vary the length of the loops during the knitting of the leg or other portions of the stocking.

A latch ring 20 is pivoted at one side of the machine upon an upright post 21 most clearly indicated in Fig. 8, and at an angle or circumferential distance of approximately ninety degrees from said post said latch ring engages and rests upon an upright post or standard 22, substantially as in the said Hemphill Patent No. 15 933,443. Depending upon the type of needle employed is the character of latch ring or its equivalent to be employed, we desirably support thereon a plurality of yarn guides at one side of the head and a single yarn guide opposite thereto, 20 as will be hereinafter more fully described, to effect the introduction at spaced points of two yarns throughout each and every course of the split work, and the interengagement of said yarns at said spaced points in the formation of suture 25 seams.

The latch ring 20 is connected with the post 21 by a pivot pin 23 and yieldingly engaging the under side of the latch ring is a spring actuated foot 24 mounted in the post 21 and adapted to exert a yielding upward action against said latch ring which, under normal conditions, is locked in its operative position against the standard 22 by a latch 25 engaging a pin 26 upon the latch ring.

The needles shown in the present embodiment of the invention are of the latch needle type, though as stated the invention is not restricted thereto, and are arranged in a circular series in number consistent with the diameter of the work 40 to be performed upon the machine. In the disclosed embodiment of the invention we contemplate the employment of 240 latch needles in a 3½ inch diameter machine. These needles are divided into two substantially equal series, those 45 of one of which have long knitting butts and those of the other of which have short knitting butts, said long butt needles being instep needles adapted to be withdrawn, preferably by elevation, at suitable times in the operation of the machine 50 by the instep cams 27, 28, shown in Figs. 4, 7 and elsewhere. These cams are arranged upon a slide 29 (see Fig. 7), arranged to slide vertically in a standard 30 secured to the cam plate 3, appropriate movement being imparted to said 55 slide 29 by means herein fully described, and which are preferably such as to permit a certain supplementary movement to be given to both instep cams for reasons hereinafter fully set forth. These connections are such that when said clutch 60 lever is in the position for rotary knitting, the cams 27, 28 will be in their lowermost or depressed positions, and when said clutch lever 14 is in position to effect to and fro or reciprocating knitting, said cams 27, 28 will automatically be 65 moved to the upper position and thereby effect the withdrawal of the instep or long butt needles, whose butts are arranged to engage said cam 27 and be depressed thereby, said cam 27 being far enough from the face of the needle cylinder to 70 engage and depress only the long butts while permitting the short butts to pass without interference. The cam 28 is, however, placed close up to the needle cylinder so as to engage either long or short butts which happen to be in their 75

elevated positions when said cam 28 and the cam 27 are depressed.

5 Mounted upon the cam plate 3 with the instep cams 27, 28 is a cam supporting block 36 (see Fig. 4, etc.) arranged to slide laterally with respect to the needle cylinder between suitable angle plates 37 positioned at opposite sides of said block and secured to the cam plate 3. A spring 38 is interposed between said cam supporting 10 block and a suitable fixed abutment 39 and constitutes means yieldingly to maintain said cam supporting block in its operative position with respect to the needle cylinder. The cam supporting block 36 constitutes the support for the so-called primary knitting cams of the machine indicated generally at A (Figs. 36, 38, etc.) and consisting of the usual stitch cams 40, 41, a lower central guide cam 42 and an upper central guide member 43. The inner faces of the cams 40, 41, 15 42, 43 are concaved and lie normally in the curve coinciding with the outer face of the needle cylinder 2.

25 The cam supporting block 36 is also provided with a pair of narrowing pickers 50, 50, pivoted upon said block in the manner characteristic of said Banner machine and arranged to operate in the usual manner. The latch ring 20 is also provided with the usual supply of yarn levers 51, herein five, referred to as the primary yarn 30 guides, said yarn levers being operated in the usual manner from the pattern drum 10 and said latch ring is also provided with at least one yarn guide 52 at the auxiliary side to supply the yarn to the instep needles and for the top of the foot 35 during split work, as will be hereinafter more fully described.

Instead of mounting the usual yarn clamping and yarn cutting devices upon the plate inside the needle circle employed in the usual Banner 40 machine and in a manner long characteristic of that machine, substantially the same yarn clamping and yarn cutting devices are mounted in substantially the same position in space upon the dial cap plate of the transfer mechanism, such 45 dial cap plate acting merely as a convenient support in their usual position for the yarn clamping and yarn cutting devices which themselves operate, in the customary manner, to cut and to clamp the yarn as will be hereinafter more fully de- 50 scribed.

The needle cylinder is provided with the usual web holder bed 57 surmounted by the web holder cam ring 58 of the usual Banner construction, having lugs to engage the latch ring 55 20 so as to effect relative movement between said cap ring and the sinker bed ring, but all of said parts being operated in the usual manner requiring no further description.

The parts hereinbefore described in detail are common to the Banner type of knitting machine and are operated automatically from the pattern shaft 9 by pattern mechanism.

An important object of the invention, as hereinbefore stated, is the provision of means whereby in one and the same machine an inturned welt may be formed upon the upper end of the stocking and split work may be formed upon other portions of the stocking.

In order to provide for the formation of split work a secondary set of knitting cams is provided, such set being indicated generally at B in the various figures. This set of knitting cams preferably includes a pair of stitch cams 62, 63, a lower guide cam 64, an upper guide cam 65 and a guard cam 66 for said upper guide cam.

The inner faces of said several cams are concaved, and are arranged to lie in a curve substantially coinciding with the curve of the outer face of the needle cylinder, which curve also coincides with the curve of the inner face of said primary set of knitting cams A. 5

Appropriate supporting instrumentalities are provided for said secondary knitting cams B to maintain such knitting cams in substantially the same horizontal plane as are the primary knitting cams whereupon certain needles including those with long knitting butts will take yarn thereat and will be actuated during the knitting of certain parts of the stocking, as, for example, the lower ankle portion or the foot, or both, and at substantially the same time that other needles including the regular short butt needles are acted upon to take yarn and knit at the primary set of knitting cams, as hereinafter more fully set forth. 10 15 20

Said secondary cams may be adjustable vertically with respect to the primary cams in order to provide perfect alignment between the two and for this purpose said secondary cams are mounted upon a plate 67 (Fig. 10) which in turn is attached to a slide 68 adjustably arranged to move vertically in the bracket 69 secured to the frame 1 by means of suitable screws. The bracket 69 may be in the form of a channel within which the slide 68 moves and means such as screws 71 extend through slots in the bracket into engagement with the slide for the purpose of fixing said slide in its predetermined adjusted relation with said bracket. Means are desirably provided to move said slide relatively to the bracket including a screw 72 having threaded engagement with a laterally projecting portion 73 of said bracket arranged beneath said slide and in its adjusted position said screw 72 is secured by a check nut 74.

In order to move the secondary knitting cams radially of the needle cylinder so as to withdraw them to position where they will not act upon needle butts, as, for example, when it is desired to replace needles by hand, the stitch cams 62, 63, and the lower guide cam 64 are mounted upon a cam supporting block 75 arranged to slide between suitable guides, said cam supporting block being yieldingly maintained in its inner position by one or more springs 77 interposed between said cam supporting block and an abutment or bracket 78. Said cam supporting block 75 is desirably left free to be retracted at will by the operator, but if desired said block may be automatically retracted, and if desired simultaneously with the retraction of the auxiliary yarn guide 52.

Such automatic withdrawal is, however, not essential and need not be resorted to.

For automatically retracting the cam supporting block 75 a lever 79 is pivoted to the under side of the plate 67, one end of said lever being adapted to engage the side nearest the needle cylinder of a pin 81 depending from the under side of the cam block as shown in Fig. 10.

There are occasions during the operation of the machine when it is desired to retract the upper guide cam 65 from its operative position independently of the cams 62 and 63. For that purpose said cam 65 is slidably mounted in the cam supporting block 75, the said cam having a slide or stem 84 arranged to slide in a suitable groove in the top of the cam supporting block, it being held within said groove by a plate 85 or other suitable means. The cam 65 is desir-

ably so mounted that it may be withdrawn either manually or automatically. For withdrawing said cam automatically we have herein represented an operating lever 86 pivoted to a stationary part of the cam support.

The lever 86 may receive its motion from any suitable means. Herein we have represented a rib 88 on the pattern drum 10 adapted to engage the cam lever 89 to rock the same about its pivot 90. The lever 89 imparts its movement in one direction, that is, when the said lever is raised by the cam 66, it moves cam lever 86 thereby retracting the cam 65, and means are provided operatively to connect said lever 86 with the lever 89, here shown as a connecting rod 91 pivotally connected at one end with said lever 89 and at its opposite end with an arm 92 secured to one end of rock shaft 93, the latter being arranged to rock in suitable bearings.

20 To the opposite end of the rock shaft 93, is secured an arm 94 which in turn is connected by means of rod 95 with one end of the lever 86. The cam 65 is yieldingly maintained in its operative position by spring 96 connected at one end to the rod 91 and its opposite end to a fixed portion of the machine frame, said spring tending at all times to maintain the operative end of the cam lever 89 in contact with the periphery of the pattern cam or drum.

30 Obviously when an auxiliary or secondary set of cams is employed, means must also be employed to feed yarn to the needles that are actuated by said secondary set of cams. For this purpose the secondary yarn guide 52 is provided 35 on the latch ring 20, as already stated, in a position appropriate to said secondary knitting cams B, herein substantially diametrically opposite to the primary knitting cams A. Said secondary yarn guide 52 is here shown as in the form 40 of a lever pivoted at 98 to said latch ring, the free end thereof being arranged to move in a suitable slot therein.

The purpose of the secondary set of cams B is principally to function the needles during the 45 knitting of split work, and where the formation of such fabric is limited to a certain portion of the stocking, as, for example, the ankle and foot thereof, said secondary yarn guide 52 must be moved into and out of its operative position 50 when said secondary set of knitting cams is moved into and out of its operative position. Preferably for this purpose the yarn guide 52 is arranged to operate automatically with the cam 65 that controls the operation of said secondary set of cams, and as a convenient means of effecting cooperation between said parts, the 55 said yarn guide 52 is provided with an extension 100 having a cam surface 101 along its under side arranged to be engaged by a lever 102 suitably pivoted to the bracket 78 and said lever has a lateral projection 104 extending underneath the extension 100 of the yarn guide 52. The lower end of said lever 102 is connected by a link 105 with the lever 86. Hence any movement of said 60 lever 86 to effect movement of the cam 65 will effect a similar movement of the secondary yarn guide 52; that is, if the cam 65 be retracted from its operative position the yarn guide 52 will be raised to its inoperative position, and vice versa.

70 In order to insure the proper engagement of the long butts of the needles with the cam 65, the guard cam 66 is mounted directly above said cam 65 with cam surfaces 66' at opposite ends thereof to cause a deflection of the needle butts 75 provided they are too high to strike the cam 65

and said cam 66 is likewise supported upon the bracket 78 by suitable means. Herein for the purpose we employ a rod or stem 106 extending rearwardly from said cam 66 into engagement with the bracket within which it is secured by 5 screws 107.

The usual widening pickers 108, 109 characteristic of the Banner type of knitting machine, are mounted upon the bracket 78 with their operative ends positioned for cooperation with the 10 cams 62 and 63. The said widening pickers are pivotally mounted upon the bracket 78, and means are provided for holding said pickers in their inoperative positions when narrowing and widening operations are not to be performed. 15 Herein for the purpose we have represented a stop plate 110 (see Fig. 10) arranged to engage the arms of the pickers 108, 109 to depress them. To control said stop plate means are shown including a bracket 111 carrying said plate and it- 20 self mounted at the upper end of a rod 112 vertically movable in the bracket 67. The lower end of said rod 112 is operatively connected with a lever 113 shown most clearly in Fig. 4 and having connections to a link 115 and a cam 116 with 25 suitable cam surfaces upon the cam 19.

We employ yarn holding and yarn cutting means for the secondary yarn as well as the main yarn, and to that end utilize the dial cam plate as a convenient support therefor, as hereinafter 30 more fully described.

Arranged at the back of the needle cylinder between the primary set and the secondary set of knitting cams is a switch cam 127 of usual construction and arranged to engage only the 35 long knitting butts and then only when the needle cylinder is travelling in a reverse direction, whereupon the said butts will be moved upwardly to the idle level for the purpose hereinafter set forth.

When the butts of the needles are passing in the opposite direction, that is, forwardly and along the usual channel for circular knitting, the long butt needles will engage said switch cam 127 and will throw the same up without changing 45 the position of the said needles. To this end the switch cam 127 is provided with a shaft 128 pivotally mounted in a fixed bracket and having a spring for normally holding said switch cam in the position shown in Figs. 52, 53, 54 and 55 50 inclusive.

Referring at this time to the operation of the needles first in plain rotary work, next in reciprocating work for the heel and toe, and then in reciprocating knitting for the formation of split work, reference is made first to Fig. 52.

In circular knitting the needle cylinder moves in the direction of the arrow in said Fig. 52, that is, toward the left viewing Fig. 52. This causes all of the needles to travel along the path indicated by the dotted lines at A*, both long and short butts passing over the stitch cam 41 of the primary knitting cams and under the guide cam 43 and the stitch cam 40 to form the usual knitting waves.

After leaving the cam 41 the needles are raised by the incline 131 on the annular ledge 4 to the normal level A* along which all of the needles pass until they strike the first stitch cam 62 of the secondary knitting set, this cam being arranged to depress all of the needles below the yarn receiving position, so that neither the long nor the short butt needles will take yarn at this time, said needles being again raised to their normal level by the incline 132. As the long 75

butt needles pass the switch cam 127 the said cam will be raised to the dotted line position shown in Fig. 52, and the short butt needles being too short to engage the cam 127 will not interfere therewith.

While the last circular course prior to the commencement of split work as, for example, at the top of the ankle portion is being knitted, the mechanism hereinbefore described is set into operation to change from rotary to reciprocating knitting, and simultaneously to raise the instep cams 27, 28 to their upper position, but the needle cylinder is not reversed until all of the long butt needles B* have passed said instep cams and been elevated thereby, Fig. 53 showing the arrangement of the long butt needles and the short butt needles E* immediately prior to the first reverse movement of the needle cylinder, the direction of which is indicated by the arrow 20 in said Fig. 53, namely, toward the right viewing said Fig. 53.

Referring at this time, for convenience of description, to the narrowing and widening operation for either the heel pocket or the toe, it is to be understood that at such time the long butt needles indicated at B* as in their upper position are not brought into operation. Therefore it is desirable that the cam 65 be withdrawn so that said long butt needles may pass along the idle level as shown at B* without interruption, the means for operating said cam 65 being hereinbefore described.

Continued reciprocating movements of the needle cylinder result in the gradual raising of the leading short butt needles by means of the narrowing pickers 50 until the desired number of courses have been knitted whereupon the widening pickers which up to such time have been held out of action by the means described 10 are released and return those needles previously raised by the narrowing pickers in reverse order to their opposite positions, thus effecting the gradual increase in the length of courses forming either the heel pocket or the toe pocket.

Having briefly referred to the formation of either the heel pocket or the toe pocket, we will now describe the operation of the parts in the formation of split work which may either precede or follow the formation of the heel pocket, 50 or both. Assuming the parts to be in the positions shown in Fig. 53, and with the needle cylinder just about to start on its reverse movement as shown by the arrow in said Fig. 53 pointing toward the right in said figure, the cam 65 being at this time returned to its operative position, the first short butt needle D* passes along to the first narrowing picker 50 and is raised to the idle or upper level of the long butt needles B*, and is thereby prevented from receiving yarn from the primary yarn guide. The needle cylinder during each reciprocating movement makes approximately a rotation, hence said elevated short butt needle D*, together with all of the long butt needles B* will pass into engagement with the cam 65 and will be caused to pass below said cam and below the stitch cam 62, thus receiving yarn from the secondary yarn guide 52 and casting thereover the previously formed loops.

Referring now to Fig. 54 and assuming all of the cams shown in said figure to be in a position similar to those of the cams in Fig. 53 with the needle cylinder having already started on its next forward movement (that is, in the direction of the arrow shown in Fig. 54—pointing

to the left in said figure) the needle E* which is the short butt needle at the opposite end of the short butt series from the needle D*, being now the first needle in the short butt series, engages the narrowing picker resting normally 5 against the top of the stitch cam 41, and is elevated by said picker to the upper level which needle thereby constitutes the last needle of the long butt series B*. The needles of the series B* which travel along the upper level engage the 10 cam 65 and are depressed thereby and beneath the secondary stitch cam 63 causing all of the needles thereof to take yarn and form stitches including the short butt needle E*. After passing the cam 63, the long butt needles pass along 15 the incline 132 and over the instep cam 27 back to the upper level, but by reason of the fact that the cam 27 is away from the face of the needle cylinder, the needle E* which has a short butt, passes up the incline 132, and then along the top 20 of the annular portion 4, which is the normal level for the short butt needles, thus joining the needles of said short butt series.

Said needle E*, however, does not move far enough to engage the picker 50 on this particular movement of the needle cylinder, and as the needle cylinder reverses before such engagement can take place, said needle E* will, upon the return movement, pass through the primary 25 knitting cams A and take its yarn in the usual 30 manner, interknitting the loop formed with the regular yarn with that previously formed from the secondary yarn, thus uniting the fabric formed upon the long butt needles which is formed from said secondary yarn, with the fabric formed upon the primary needles to which the primary yarn is advanced in the usual manner.

Upon the next reverse movement of the cylinder as shown in Fig. 55, the needle D* will again be raised by the narrowing picker 50 of the primary set to the upper position and will pass over the primary knitting cams A and through the secondary set of knitting cams B, thus taking 40 yarn from said secondary yarn guide 52, and casting 45 its loop. The long butt needles B* after passing through the secondary set of cams B in the direction of the arrow shown in Fig. 55 will be raised to their upper level by means of the switch cam 127, but the needle D* not having a 50 long butt, and in view of the fact that said cam 127 is placed at a distance from the needle cylinder and can be engaged only by the long butts, will pass along the normal level of the needles of the course C*, and thence through the primary 55 knitting cams A and receive a yarn which is interknit with the previously formed loop of the yarn received at the secondary knitting cams B, thus repeating the operations previously described. That is to say, the two end short butt needles D* and E* 60 (at the two ends of the short butt series) knit alternately with both threads, (first at one side of the machine with the long butt needle at the secondary side and then with the short butt needles at the primary side) to make the suture needles. To do this, it is necessary in the disclosed embodiment of the invention to use lifting or narrowing pickers 50—50 alternately to elevate 65 said needles which are later depressed as they knit at the secondary cams.

We have thus far described the knitting of the stocking excepting the welt, to the formation of which the invention is particularly directed, both in and of itself and in cooperation and combination with the split work of the stocking either in 70 75

the ankle or the foot portion or both. The effective cooperation of the instrumentalities for the formation of the welt and of the split work will be hereinafter more fully set forth, it being sufficient to state at this time that one of the difficulties heretofore experienced in the formation of a welt has arisen from the presence of the float threads incident to the reinforcement of the high splice and the sole of the foot. These float threads are very difficult to handle or to keep out of the way of the dial and have necessitated the provision of additional instrumentalities to manipulate them, and prevent their entanglement with the mechanism or parts of the dial. 10 By forming split work we avoid the formation of float threads and hence avoid the necessity for providing means to prevent the entanglement of float threads with the dial or parts associated therewith. 15 Before describing in detail the mechanism for forming the welt we will state the general operation or steps that are carried out to effect the formation of the welt and for that purpose will assume that the toe of the preceding stocking had just been completed. 20

Immediately following the formation of the toe all the needles operate in the usual way to knit the "looper-round" which as is well known is provided to facilitate the seaming of the toe. 25 Thereupon we throw in a breaking thread for a few courses, (one or more), as in the preferred embodiment of the invention we knit the stockings in a continuous string and break them apart after a series of them have been completed, by 30 parting said breaking thread. Within the broad scope and purpose of the invention, however, we may drop off each stocking and in Figs. 79 to 84 show means whereby this may be accomplished.

Having knitted in the breaking thread for a sufficient number of courses we now proceed with the formation of the welt and for that purpose we have provided an auxiliary drum, the movement of which is commenced at this time. We provide as heretofore long and short butt needles 45 in desirably equal number and arranged as is usual in the formation of the stocking, namely, with the long butt needles positioned for the formation of the instep and the short butt needles for the formation of the heel and toe. We 50 provide a jack under each needle and for that purpose have four different shapes or forms of jacks, namely, long-butt long jacks, short-butt long jacks, long-butt short jacks and short-butt short jacks. The specific arrangement of these 55 jacks will be hereinafter pointed out, it being here stated that in the desired arrangement, the jacks are alternately long and short, there being long butt jacks under long butt needles and short butt jacks under short butt needles, the first long 60 butt needle desirably having a short-long butt jack.

In accordance with the first disclosed embodiment of the invention, we employ a dial having a transfer point or transfer jack for each needle, 65 which point or jack may be referred to generally as a transfer instrument. An underlying feature of the first disclosed embodiment of the invention is the loading of the transfer points or jacks by predetermined selection of the needles and their projection in separate groups or series instead of immediate or uninterrupted succession. For example and as shown in the first represented embodiment of the invention, we first load the transfer points or jacks from every other needle and 70 then again load the transfer points or jacks from

the remaining needles. Within the scope of the invention, however, we may otherwise divide or group the needles to effect the transfer of loops to the transfer points or jacks, as, for example, by loading first from one third of the needles, 5 then from a second third and then from the remaining third, or we may even divide or group the needles so as to load first from one quarter of the needles, then from the second quarter, then from the third quarter and finally from the remaining quarter thereof. In any of these cases 10 the needles from which jacks are loaded at any one loading course are desirably distributed about the entire circle of the needles and are not arranged in immediate succession. For example, 15 in loading the transfer points or jacks by selection of the needles by thirds we would desirably load at one course from the first, fourth, seventh, etc., needles, on the next course from the second, fifth, etc., and on the third course from the third, sixth, 20 etc. If we desire to load the transfer points or jacks by selection of the needles by fourths, we would on the first course load from the first, fifth, etc., needles, on the second course from the second, sixth, etc., needles, on the third course from 25 the third, seventh, etc., needles, and on the fourth course from the fourth, eighth, etc., needles.

In certain classes of work, as, for example, so called accordion work, we may load the transfer points or jacks from the needles unevenly or 30 irregularly, according to the pattern, as, for example, in the first course from the first, third, sixth, eighth, tenth, etc., and in the next course from the second, fourth, seventh, ninth, eleventh, etc. 35

Obviously the invention is not limited to the number of divisions of the needles, but desirably we load the transfer points or jacks either in two operations, thus loading from alternate needles or in three operations, and herein we have specifically disclosed the loading of the transfer points or jacks in two operations, it being understood that in such first represented embodiment of the invention all the points or jacks receive yarn in each course or step inasmuch as the loop from each selected or projected needle is received not only by the corresponding point or jack, but also by the next proper jack in advance thereof, as will be evident from Figs. 48 and 50. 40

Assuming for convenience of description that we load the transfer points or jacks in two courses, and referring to the first illustrated embodiment of the invention, where such action is indicated as performed, the needles are divided into a number of groups corresponding with the described group or selection thereof. Therefore we, in such case, provide means to raise every alternate needle through out the circle of needles, so that its loop may be loaded upon the corresponding transfer point or jack (as well as upon the point or jack next thereto in advance), and then we depress the said needles and elevate all the remaining needles so as to complete the loading of the transfer points or jacks. For this purpose we provide certain additional cams among which are three radially or otherwise in-and-out movable cams hereinafter referred to as cams 140, 141, and 143. Also we provide in the disclosed embodiment of the invention one extra stationary cam and we impart an extra movement to the usual instep cams 27, 28. These movable cams are arranged about the cam ring and control the needle jacks for the presentation of the needles in groups for the 45 50 55 60 65 70 75 80 85 90 95 100

loading of the transfer points or transfer jacks. The transfer points or jacks are arranged within a dial and are radially moved therein by means of cams which desirably include a loading cam and an unloading cam both mounted on vertical pivots for in and out movement instead of being mounted for up and down movement toward and from the face of the dial. The said cams of the dial are automatically controlled from the auxiliary drum as are also the cams which control the needle jacks.

In effecting the formation of the welt, there are six general positions of the parts which we will now briefly refer to so that the general operation may be in mind in the reading of the ensuing description of the details of the mechanism first disclosed.

Position No. 1.—In this position of the parts the breaking thread or yarn is thrown in for a few courses. For this position the auxiliary drum begins to move by suitable lever and pawl mechanism and all the needle jacks are down.

Position No. 2.—For this position cams 140 and 141 are moved in. All the needles are withdrawn by cam 140. Cam 141 raises all the jacks, but the short jacks are not raised high enough by cam 141 to come into contact with their needles. Therefore the needles with short jacks underneath them ride under the knitting cams, while the needles with the long jacks underneath them go through the knitting cams in the usual way. In this position cam 143 is out. One turn of the needle cylinder accomplishes the foregoing which effects the formation of the first antiravel course, it being noted that the jacks are at two levels.

Position No. 3.—At the end of one revolution of the needle cylinder cam 140 is withdrawn, cam 141 being still in, and cam 143 being still out. The short jacks which had been elevated ride up the stationary cam (before they had ridden under it). This makes the needles for the short jacks clear the first cam of the knitting cam set. One revolution of the needle cylinder is made and 45 in doing so the entire circle of needles knits.

Position No. 4.—At the end of said revolution cam 141 is withdrawn and cam 143 and cam 140 go in. Cam 140 pushes all the needles down and the needles having short jacks beneath them 50 rise up and go through the ordinary knitting cams because of their short jacks riding on the stationary cam. Therefore only the needles having the short jacks knit, said needles being indicated as the elevated needles in Fig. 48. Just as each of said needles has taken the thread and is being moved down to knit or cast off, the transfer jacks begin to come out. Although only alternate needles knit, all of the jacks are moved out and stay out for two revolutions, and the 55 loading of the jacks occurs in this position. Desirably at the beginning of the fourth position we put in an extra yarn for strength as one yarn might be cut in the stretching thereof across the transfer points or jacks. Such extra yarn 60 desirably stays in for about two courses. Thus at this time two yarns are stretched across the projected transfer points or jacks. Position No. 4 occupies one course.

Position No. 5.—Cams 140 and 143 are in, and 70 cam 141 goes in. This position consumes two courses, in the first course of which the dial transfer jacks operate and in the second course of which the said dial jacks are out of operation. For or in position No. 5, the opposite needles are 75 brought up, namely, the remaining needles not

raised at the first loading action, such opposite needles being indicated in Fig. 50. It is to be noted that in position No. 4 the short jacks ride up the stationary cam and therefore they cause their needles to knit. In position No. 5 the short jacks ride under the stationary cam and therefore they do not elevate their needles, but the long jacks are pushed up by cam 141 which as stated goes in at the beginning of position No. 5, and the result is to cause the needles corresponding to the long jacks to knit, it being understood that the transfer points or jacks are still projected and therefore all the transfer points or jacks are loaded from the said opposite needles. (Fig. 50.) During the second revolution or course of position No. 5 all the transfer points are retracted, holding the yarn.

Position No. 6.—At the end of the second course of position No. 5, the instep cams 27, 28 rise high enough to throw the long butt needles 20 over cam 140, therefore allowing cam 140 and cam 141 to be withdrawn, cam 140 being withdrawn first. Cam 143 is in action from this time on.

The instep cams 27, 28 are also moved down 25 about this time. The machine now goes onto plain knitting and any length desired is knitted (that is, twice the length of the desired welt). Then all the jacks are projected during two revolutions, their loops being transferred to their 30 respective needles and the machine goes into the knitting of the regular plain work of the leg.

Having thus referred to the steps which are carried out for and in the formation of the welt, we will now describe the mechanism by which the 35 foregoing operations are carried out.

The needles are arranged in two groups, namely, short butt and long butt needles, the long butt needles knitting the instep and the short butt needles knitting the heel and toe.

Referring more particularly to Figs. 36 to 47, a few of the short butt needles are indicated at 40 133, and a few of the long butt needles at 134. Beneath each needle is positioned in the groove thereof a jack which is wholly distinct and independent from its needle and which in its retracted position is vertically spaced from its needle so that a considerable lengthwise movement of the jack is necessary before it engages its needle for moving the same upwardly.

It will be understood that as here disclosed the long butt needles are arranged at one side of the cylinder and number one half the needles consecutively arranged. At the other side of the cylinder are the short butt needles consecutively arranged. Under each long butt needle is a long butt jack, but the stems of said jacks are alternately long and short. Under each of the short butt needles is a short butt jack but the stems of these jacks are alternately long and short. Thus throughout the entire circle of needles the stems of the jacks are alternately long and short. In Figs. 37, 39, 41, 43, 45 and 47 are indicated certain of the said needles and their jacks. Referring for example to Fig. 37, the first needle reading from the right has a short butt. Beneath it is a long jack 135 which has a short butt 45 136. Under the next needle is a short jack 137 having a short butt 136. Under the next needle is a long jack 135 having a short butt 136. Under the next needle is a short jack 137 having a long butt 138 and under the next needle, being the last of the needles there shown, is a long jack 137 having a long butt 138. It will be ob-

40

served that the first long butt jack reading from the right is under the first long butt needle.

The two parts of the instep cam are indicated at 27 and 28 in Figs. 36, 37, 38, etc. Immediately

5 to the left of said cams is the extra cam 140 so-called. As herein shown, beneath the cam 140 is positioned extra cam 141, and immediately above the same is the stationary cam 142. Beyond the stationary cam 142 and to the left there-

10 of viewing Fig. 36 is the extra cam 143 so-called.

The mounting of these cams and their immediately associated means for operating the same will now be described.

Upon the base or support 144 shown in Figs. 15, 16 and elsewhere, is an upstanding block 145 in which is mounted for sliding movement cam

140, it having imparted thereto an in-and-out or radial movement by means of a bellcrank lever 146 pivoted at 147 upon an ear or bracket and

20 having an arm 148, the end of which is extended into a notch 149 at the side of said cam 140.

The opposite arm 150 of said bell crank lever has a pin 151 which engages a lengthwise slot 152 in a downwardly extending link or rod 153. At

25 the upper end of said rod 153 is a pin 154 to which is connected a coiled tension spring 155, the lower end of which is connected to the pin 151 upon the lever arm 150. The construction

30 and operation are such that in the upward movement of the rod 153 the cam 140 is not moved positively inward until the lower end of the slot 152 engages the pin 151, but previous to that time the spring 155 in the upward movement of the rod 153 tends through tension to move the

35 cam 140 inward, but yieldingly against possible resistance of the needle butts. Upon the downward movement, however, of the rod 153 the cam 140 is positively withdrawn at once because of the engagement of the upper end of the slot 152

40 with the pin 151 upon the lever arm 150.

Cam 141 shown in plan in Fig. 12 and in elevation in Figs. 17 and 18, is mounted for radial sliding movement in a bracket 156 secured by screws 157 to the framing. The inner edge of

45 such cam 141 is arranged concentrically with the circle of the needle cylinder and said cam is arranged at an incline as most clearly indicated in Fig. 18 as well as in Figs. 36, 38, etc. It is shown as directly beneath, is spaced from

50 and is parallel with stationary cam 142, the latter being desirably an integral part of the housing of cam 141. In order to impart radial movement to said cam 141, the stem 158 of said cam is notched at its edge as indicated at 159 for

55 the engagement of the end 160 of a lever 161 pivoted at 162 upon the framing. The opposite end of said lever is pivotally secured at 163 to a horizontally extending link 164, the connections to which will be hereinafter described.

60 Cam 143 is mounted for radial movement in a bracket or housing 165 also mounted upon the bed plate to which it is secured by screws 166. Said cam 143 has its inner edge concentrically arranged with respect to the surface of

65 the needle cylinder and is also arranged at an incline as most clearly indicated in Fig. 19 as well as in Figs. 36, 38, etc. Said cam is provided with a stem 167 to which is pivotally connected at 168 a bell crank lever 169 pivoted at 170 upon

70 an ear extending from the bracket 165. The arm 171 of said bell crank lever is slotted for the reception of the pin 168 and the opposite arm 172 of said lever is pivotally connected at 173 to a horizontally extending rod 174, the connection to which will be hereinafter fully described.

In each of Figs. 36, 38, 40, 42, 44 and 46 the main cam knitting set is indicated at A and the auxiliary or secondary knitting cam set is indicated at B.

In Fig. 36 is indicated position No. 1 previously referred to, this being the position when the breaking yarn is thrown in for one or more courses. Such yarn is desirably supplied by one of the yarn fingers at the main knitting cam set A other than the finger supplying the main knitting yarn. Viewing Fig. 36, it will be observed that all the jacks both long and short are down and that knitting occurs wholly at the main knitting cam set A as indicated by the dotted lines representing the needle butts. At 15 the auxiliary knitting cam set B the needles pass through the cams without knitting as indicated by the said dotted line. In this position the instep cams 27, 28 are in their usual position and the cam 140 is out.

In position No. 2, shown in Fig. 38, cam 141 raises all the jacks as clearly indicated in said figure, but as therein shown the short jacks are not raised high enough by said cam 141 to cause them to come into contact with their needles, 25 and therefore the needles pertaining to said short jacks ride under the main knitting cam set A, as plainly indicated in dotted line at 175, whereas the needles with the long jacks underneath pass through the main knitting cams A 30 in the usual way and knit thereat, thus accomplishing the first anti-ravel course. In this position the instep cams 27, 28 are still in the same position but the cam 140 is in.

In position No. 3 shown in Fig. 40, cam 140 35 being out, cam 141 being still in and cam 143 being still out, the short jacks which had been elevated ride up the stationary cam 142 as shown in said figure, whereas previously they had ridden under said cam 142. This causes the needles having the short jacks to clear the first cam of the main knitting cam set A as indicated by the dotted line. Thus every needle knits at the main knitting cam set A, but none of them knits at the auxiliary knitting cam set B.

40 At the end of a single revolution the necessary cams are shifted so as to bring them into position No. 4 shown in Fig. 42, cam 141 being out and cams 140 and 143 going in. Cam 140 pushes all the needles down as indicated by the dotted line in Fig. 42 and the needles with the short jacks beneath them rise and pass through and knit at the main set of knitting cams A, inasmuch as said short jacks ride upon the stationary cam 142. Only the needles with the said short jacks knit at this position. The transfer points or jacks begin to come out just as the elevated, alternate needles which are shown in Fig. 48, come down to knit, and the loops are loaded onto all the transfer points or jacks, but from alternate needles only in the first embodiment of the invention disclosed, as hereinafter explained.

45 Position No. 5 is indicated in Fig. 44, cam 140 being in, cam 141 going in and cam 143 staying in. In said position No. 5, the short jacks ride under the stationary cam 142 and therefore they do not elevate their needles, but the long jacks as there shown are elevated by cam 141 which goes in at the beginning of position No. 5 and these long jacks cause their needles to knit at the main set of knitting cams A as clearly indicated in Fig. 44. As the said needles—being those indicated as elevated in Fig. 50—descend to knit, 50

their loops are loaded onto all the transfer points or jacks, which are still out.

Position No. 6 is indicated in Fig. 46. As therein shown, the instep cams 27, 28, rise high enough to throw the long butt needles over cam 140 as indicated by the dotted line in said Fig. 46, thereby permitting said cam 140 to be withdrawn, almost simultaneously with which withdrawal cam 141 is also withdrawn.

10 We will now describe in detail the structure of the dial and the parts immediately associated therewith including the transfer points or transfer jacks and their operating means.

15 Referring more particularly to Figs. 8, 10, 13, 14, and 30 to 35, it will be observed that formed integrally with or secured to the latch ring post 21 as clearly indicated in Fig. 8 is secured a hub 176 wherein is mounted an upright post 177, it having an eccentric portion 178 indicated in Fig. 20 12 for the purpose of accurately centering or laterally adjusting the dial and directly associated parts within the needle circle. Upon said post 177 is fixedly secured by set screw 179 a collar 180 in which are mounted vertically positioned 25 set screws 181 held in proper adjusted position by nuts 182. This permits the ready adjustment of the said screws. Loosely mounted upon the post 177 is a sleeve like bracket 182, which may be held tightly in operative position by a set screw 30 183. Laterally extending from said bracket 182 is a web 184 at the outer end whereof is a hub 185 wherein is received for rotation a stud 186 which, as clearly shown in Figs. 31, 33, is provided with a head 187. The upper half or portion 35 of said stud 186 is threaded as indicated at 188 for a purpose to be hereinafter described.

It will be observed that the dial with its transfer points or jacks and the dial cover or cap and parts thereof may be readily and quickly swung 40 from their operative position within the circle of needles by loosening the set screw 183, slightly lifting the bracket 182 from the supporting ends of the screws 181 and swinging the parts into the position shown in Fig. 14, for the purpose of permitting access to the interior of the needle cylinder or for any other reason.

The dial is shown at 189 in Figs. 31, 33, 35, etc. It is mounted for rotative movement with and by the needles as hereinafter stated, upon the stud 50 186, having a nice fit thereon to rotate therewith. It is provided with radial grooves 190 corresponding in number with the entire number of knitting needles in that embodiment of the invention first illustrated. In each of said grooves 55 is positioned a transfer point or transfer jack 191 of the shape fully indicated in said figures and also in Figs. 56 and 57. That is to say, each transfer point or transfer jack is straight, parallel sided throughout its entire extent having straight upper and lower edges and each is provided with an upwardly extending butt 192, and all the butts are of the same length. At the outer end of each transfer point or jack is the hook portion 193 which is upwardly curved as indicated, the side 65 faces of said hook being desirably straight continuations of the parallel side faces of the body of the transfer point and jack. Desirably and as shown in Figs. 56 and 57, the hook portion in the rear of the upwardly extending portion of the 70 hook is thicker than is the body of said transfer point or hook for the purpose of strengthening the hook and better adapting the hook to receive and support the loops when loaded thereon. For example, each transfer point or hook is in 75 the body portion desirably about .010 of an inch

thick whereas the width of the hook portion directly in the rear of the upwardly bent hook proper as at 194 is desirably .015 of an inch.

The dial cap is indicated at 195 in the several figures. It is provided with a disk like portion 5 overlying the dial 189 and with a hub portion 196 loosely mounted upon the stud 186 and upon the upper end of which hub 195 bears a collar 196A, and upon the latter bears a collar 196B having therein a screw 196C shown as somewhat pointed 10 to enter between the threads 188. Said collar 196B can be readily brought into position to hold the dial cap from turning by holding the collar 196B tightly in position and the screw then tightened in position. When desired, the dial cap can 15 be readily released, but it is held without turning movement during the knitting operation.

The hub 196 of the dial cap 195 is annularly recessed as indicated in Figs. 31, 33 and 35 for the reception of ball bearing means herein shown 20 as consisting of a ring 197 in direct contact with the stud 186 and in actual operation permissibly turning thereon. Said ring 197 is annularly grooved at 198 for the reception of an annular series of balls 199 which engage an annular groove 25 200 in outer ring 201 pressed into the hub 196. Above and below the balls 199 are the rings 202, 203 of the cage. This construction permits the free and ready rotation of the dial and its stud 30 186 with and by the needles, as hereinafter described. Upon the under side of the dial cap are mounted the loading cam 204 represented as pivoted for in and out movement at 205, and transfer cam 206 represented as pivoted at 207 for in and out movement. Between said two cams are the 35 stationary cam portions 208 and 209.

The under face of the dial cap is provided with an annular shoulder clearly indicated in the several Figs. 31, 33, 35, at 210, and about said shoulder and engaging therewith at its concentric portions, is provided a stationary cam ring 211 fitted onto the lower face of the dial cap and intended to guide or direct the butts of the transfer points or transfer jacks past the loading cam 204 and the transfer cam 206. The outer edge 212 of the stationary cam ring 211 is concentric with the stud 186 and the shoulder 210, and fitted against so as to turn about said concentric edge 212 is a so-called floating ring 213. Said floating ring under the influence of and driven by the needles, turns about, with the dial, on the outer edge of the stationary cam ring 211. It has no movement independently of the dial, being driven by the needles and thereby turning the dial through its engagement with the transfer points or jacks in the grooves of said dial. Said floating ring upon its under face is provided with radial slots 214 equal in number to the number of the transfer points or jacks and in which slots said transfer points or jacks move radially through the action of the loading cam 204 and the transfer cam 206. This floating ring therefore provides not only a driving means for the dial, but also a truing means for the transfer points or jacks and compels their hooked ends to be presented with absolute accuracy between the needles which rise therebetween at the proper times as indicated in Figs. 31, 33 and 35, thereby driving the floating ring.

The outer edge of said floating ring 213 is 70 provided with a series of teeth 215 in radial line with the radial slots 214, and thus providing a series of grooves or spaces between such teeth and between the radial grooves 214, equal in number to the entire number of the needles, which 75

therefore in their vertical motion in their grooves in the cylinder wall rise between said teeth and are trued thereby, so that they are presented with absolute accuracy to the hooks of the transfer 5 points or jacks 191. This needle truing function of the floating ring is reciprocal to the driving action of the needles in thereby rotating the floating ring and within the scope and purpose of the invention these reciprocal functions of the 10 floating ring and needles may be used in other types of machines and in such case the floating ring would be located below the plate carrying the binder and severing means and would be devoid of grooves upon its lower face.

15 Said floating ring constitutes an important feature of the invention. In the represented form thereof it is an annulus fitting for rotation onto the outer edge of the stationary cam of the dial cap and is driven by the needles in the rotation 20 of the needle cylinder and so itself drives the dial through said transfer points or jacks. It is toothed and itself straightens the needles, straightens the jacks and drives the dial. Each of the said three functions is of importance irrespective of the others, and whether or not the floating ring be employed to drive the dial. The jack straightening function may in certain embodiments of the invention be employed whether or not the needle straightening function is employed and the latter function may be employed in other embodiments of the invention without the jack straightening function.

25 The said floating ring in various embodiments thereof may be employed upon a ribber as well as upon a wester, and even upon a plain machine, and therefore we claim the same broadly. Other uses of said ring it is not necessary here to refer to.

We will now described the disclosed means for 40 operating the movable cams which control the jacks for the needles and the disclosed means for operating the loading cam and the transfer cam of the dial and will for that purpose refer more particularly to Figs. 4, 5, 12 and 21 to 28.

45 Not only does the pattern shaft 9 have fast thereon the usual pattern drum 10, but it has loose thereon a series of five disk like or peripheral cams 216, 217, 218, 219, 220 shown in Figs. 22 to 26 respectively but which preferably are 50 formed in one piece, and constitute the auxiliary drum. Said pattern shaft 9 has fast thereon by means of a set screw 221 a disk like cam 222 shown in Fig. 28. Said cams are arranged in the order referred to upon the pattern shaft 9 reading from 55 the right in Fig. 4, but between said disk like cam 222 and cam 220 is the ratchet 223 which by means of screws 224 is made fast to the entire series of disk like cams 216 to 220,—that is, to the auxiliary drum,—which therefore turns upon 60 the pattern shaft 9 through the influence of the ratchet 223 and the movements of said ratchet are controlled by the contour of the outermost disk like cam 222 which as stated is fast on the shaft 9.

65 As shown most clearly in Fig. 5 said cam 222 is provided with a cut away portion 225, the rest of the peripheral portion of said cam being concentric with the shaft 9 as indicated at 226. The height of said concentric portion 226 of the cam is such as to shield the teeth 227 of the ratchet from engagement by the pawl 228, but when the recessed portion 225 has been brought into proper position the pawl 228 engages a tooth 70 of the ratchet and thereafter the ratchet is

turned in a step by step manner, carrying with it the several disk like cams 216 to 220.

Fast upon the main shaft 5 of the machine is a crank disk 229 shown most clearly in Fig. 5 and suitably secured thereto to constitute a crank 5 member is the rod 230 suitably guided in the framing by means of a pin 231 upon the framing taking into a longitudinal slot 232 in said rod. The lower end of said rod is bent as indicated at 233, and at 234 it is pivoted to the end of a 10 yoke 235, the other end of which yoke takes loosely about the pattern shaft 9. Pivotedly mounted upon the arm of the yoke at 236 is the pawl 228 which thus in the rotation of the main shaft 5 is constantly moved but drives the 15 auxiliary drum only when the teeth of the ratchet 223 are exposed at the proper time in the rotation of the pattern shaft 9 as previously stated.

The peripherally positioned cams upon the disk like members 216 to 222 inclusive are relatively arranged in the positions indicated in Figs. 22 to 28, and in the relative order indicated they operate through the connections which we will now describe the three cams 140, 141 and 143 which control the jacks for the needles, and the 25 loading cam and the transfer cam for the transfer points or jacks, and also impart an auxiliary movement to the instep cams 27, 28, for a purpose to be hereinafter set forth. Cam 140 is controlled by the disk cam 220; cam 141 is 30 controlled by the disk cam 216; cam 143 is controlled by the disk cam 218; the loading cam of the dial is controlled by the disk cam 219; the unloading or transfer cam of the dial is controlled by the disk cam 222 and the auxiliary 35 movement of the instep cam is controlled by the disk cams 217.

We will now describe in detail the connections from each the said disk cams to the parts controlled thereby.

40 *Connections for operating cam 140.*—Cam 140 is controlled by the disk portion 220 of the auxiliary cam. To that end there rests upon said disk portion, as shown most clearly in Figs. 5 and 26, a lever 237 pivoted at 238 to the upwardly extending link 153 shown in Fig. 5, and the upper part whereof is shown in Fig. 15. The connections from said link 153 to said cam 140 have already been described.

45 *Connections for operating cam 141.*—Cam 141 is controlled by the cam disk portion 216 of the auxiliary drum, said disk portion being shown most clearly in Fig. 22. To that end, a lever 239 is provided to bear at its free end upon said disk portion as shown in Fig. 22. Said lever 239 is pivoted at 240 shown most clearly in Fig. 5, and the rear end 241 of said lever is pivotally connected at 242 to a rod 243 whose upper end is pivotally connected at 244 to the arm 245 of a bell crank lever pivoted at 246. The opposite arm 247 of said lever is pivotally connected at 248 to the horizontally positioned link 164 shown most clearly in Fig. 12. The connections from said link to cam 141 have already been described.

50 *Connections for operating cam 143.*—Cam 143 is controlled by the cam disk 218 of the auxiliary drum, said cam disk being most clearly illustrated in Fig. 24. To that end, said cam disk is engaged by the end of a lever 249 shown most clearly in Fig. 24. Said lever 249 is also pivoted at 240 and the opposite arm 250 of said lever, as most clearly shown in Fig. 5, is pivotally connected at 251 to a rod 252 extending upwardly therefrom, and connected at 253 to another bell crank lever also pivoted at 246. Said bell crank 55

lever has two arms 254 and 255, the latter being pivotally connected to the link 174 shown most clearly in Fig. 12. The connections from said link 174 to cam 143 have already been described.

5 *Loading cam 204 for transfer instruments.*—

The loading cam 204 of the dial cap shown most clearly in Figs. 30, 32 and 34 is controlled by the disk portion 219 of the auxiliary drum, said disk portion being most clearly shown in Fig. 25.

10 Bearing upon the said cam disk is the end 256 of a lever pivoted at 257 (see Fig. 5). The opposite arm 258 of said lever is pivotally connected at its outer end to a link 259 which at its upper end is pivotally connected at 260 to a lever arm

15 261 which is connected to an upwardly extending link 262. Said link at its upper end is pivotally connected at 263 to a lever arm 264 shown also in Fig. 8, as pivoted at 265. Said lever has an upwardly extending arm 266 whose upper

20 end is forked as indicated most clearly at 267 in Fig. 9. Said forked end receives the bent end 268 of a slide 269 which is pivoted at 270 to a link 271 itself pivoted at its other end at 272 to a lever 273 fast to the upright pivot 205 of the

25 loading cam 204 shown in Figs. 30, 32 and 34.

Transfer cam 206 for transfer instruments.—

The transfer or unloading cam 206 for the transfer instruments is controlled by the disk cam 222 shown most clearly in Fig. 28 and previously de-

30 scribed as fast upon the pattern shaft 9. To that end there bears upon said disk cam 222 the free end of a lever 274 shown in Fig. 28, and also indicated in Fig. 5 as pivoted at 257. The opposite arm 275 of said lever is pivotally connected

35 at 276 to an upwardly extending link 277, to the upper end whereof is pivoted at 278 the arm 279 of a bell crank lever pivoted at 280. The opposite arm 281 of said bell crank lever extends upward as indicated in Figs. 5 and 8 and is there

40 forked as indicated at 282, shown also in Fig. 9, to receive the bent end 283 of a slide 284, pivotally connected at 285 to a link 286 itself pivotally connected at its opposite end at 287 to a lever 288 fast upon the upright stud 207 of the

45 transfer or unloading cam 206.

Additional movement of instep cams.—An additional movement, as heretofore indicated, is imparted to the instep cams 27, 28. For that purpose and as shown most clearly in Figs. 23 50 and 4, 5 and 7, the disk cam 217 forming a part of the auxiliary drum and as shown most clearly in Fig. 23, has resting thereon the end of a slide 289, shown also in Figs. 4 and 7. The upper end of said slide takes against the under side of the block 290 forming a part of the connections to the instep cams 27, 28. Said block has therein a slot 291 shown as having an intermediate inclined portion and two end portions which are parallel to each other and which extend vertically. Within said slot is received a pin 292 which is connected to a short link 293 itself pivotally connected at 294 to the arm 295 of a lever pivoted at 296 and having an arm 297 pivoted at 298 to the block carrying the instep cams. It will be observed that an upward movement of the slide 289 moves the block 290 upward and therefore moves the pin 292 to the left viewing Fig. 7 and therefore moves the instep cams 27, 28 to an intermediate position.

70 *The work holding sector.*—Desirably we provide means to hold the work against the under side of the dial during the formation of the welt so that it will not interfere with the proper needle action. For this purpose we have in Figs. 9, 11 and elsewhere represented a so-called sector 299.

This sector, which may have any suitable form, is desirably in its inner or operative position at all times excepting when the needle cylinder is reciprocated. At such times the sector is moved out, desirably automatically, in order to clear the needles. Therefore in the disclosed embodiment of the invention, the sector 299 is moved out for the formation of the high splice and double sole, both of which are formed by split work, and also for the heel and toe, but is not moved out for yarn changing. An instrument for this general purpose of holding work against the under side of the dial has heretofore been employed in certain cases but positioned substantially at the yarn guides so that it must be moved out of operative position to permit a yarn to pass into the binder and another yarn to be removed from the binder. We, on the contrary, position the sector at a side or point of the machine relatively remote from both the main and the auxiliary yarn guides, as clearly evident from both Figs. 9 and 11, and it is therefore unnecessary to throw said sector out of operative position to permit yarn change. During reciprocating motion the sector is, however, out of operative position as otherwise the elevated needles would strike the same. In rotary work the needles when they reach the location of the sector are down and therefore cannot strike the same. In split work, however, certain of the needles would be projected at the auxiliary side to take the auxiliary yarn and would strike said sector.

As shown most clearly in Fig. 11, the sector 299 is secured by screws 300 upon an arm 301 pivoted at 302 upon a bracket 303 on or integral with the post whereto the latch ring is pivoted.

In dotted lines in Fig. 11, we have indicated at 304 the horizontally movable link which is pivotally connected to and moved by the clutch lever 14. The outer end of said link 304 bears against 40 the bent end 305 of a slide 306 shown also in Fig. 4 and there represented as guided in supporting brackets 307, 308. The outer end of said slide 306 is inclined as indicated at 309, so as to provide a wedge and takes under the lower end 310 of a 45 vertical slide 311 guided in suitable brackets 312. The upper end of said vertical slide 311 is itself inclined or wedge shaped as indicated at 313 and against it bears the inner edge of the pivoted arm 301 as indicated most clearly in Fig. 11. 50 Said arm 301 is held in contact with the inclined end of said slide 311 by a coiled spring 314 connected at 315 to a suitable part and at 316 connected to the arm 301. The pin 315 is desirably mounted upon the auxiliary cam block and 55 thereon is secured an adjustable stop 317 to be engaged by the inner edge of the arm 301. In Fig. 11, the sector 299 is represented as in its inner position above the sinkers so as to hold the work up against the bottom of the dial, whereby 60 the new work coming from the needles has a free opportunity to pass down into the cylinder.

We have in the preceding description referred to that embodiment of the invention wherein the transfer points or transfer jacks equal in number the needles, and we have in Figs. 48 to 51 indicated somewhat diagrammatically the manner in which the loops are transferred to the transfer points or jacks in a plurality of courses, herein shown as two. Preferably, however, we employ only half as many transfer points or jacks as there are needles in the entire circular series, but in such case we do transfer in a plurality of steps or courses all the loops from the entire circle of needles to said lesser number of transfer points. 70 75

In Figs. 64, 65 and 74, we have indicated the preferred mode of transferring when employing only half as many transfer points or jacks as needles, and in Figs. 66 to 78 we indicate diagrammatically 5 other methods of transferring, all being within the broad scope and purpose of the invention. Preferably, however, the method employed by us is that indicated in Figs. 64, 65 and 74.

The invention, involving as it does the use of 10 transfer points or transfer jacks, is radically distinguished from mechanisms or methods wherein dial needles are employed, acting in conjunction with cylinder needles, to form an inturned or other welt.

15 We are aware that it has been proposed to employ a set of dial needles, an instance thereof being illustrated in the British patent to Stibbe No. 13,307 of 1914. The disclosure in said patent is of the formation of two setting-up courses 20 wherein the cylinder needles are projecting in two series respectively including alternate needles, but in such cases the thread is initially laid upon the projected dial needles as well as upon the cylinder needles, and not only are the loops 25 not loaded from the cylinder needles onto the dial needles, but the employment therein of dial needles precludes the accomplishment of many important results secured by the invention.

It is pointed out that the use of dial needles 30 as the instrumentalities to receive the loops or so-called quasi-loops of Stibbe, involves the making of enlarged loops in transferring the loops or quasi-loops back onto the cylinder needles. As shown in Fig. 12 of the said patent to Stibbe 35 and as disclosed in the specification of said patent, it is necessary to cast off the said loops or quasi-loops over the latches of the rib needles, thereby unduly enlarging the loops. Such enlargement is avoided by the use of transfer 40 points as disclosed in this application. Moreover the use of latch needles involves the complicated dial structure disclosed in Fig. 14 of the Stibbe patent.

Referring more particularly to Figs. 64 and 45 65 wherein diagrammatically the loading is indicated in two courses while employing only half as many transfer points or jacks as we employ cylinder needles, and referring also to Fig. 74 wherein the distribution of the loops as loaded 50 onto the transfer points is more clearly indicated, we have therein indicated in Fig. 64, at 318, the alternate needles of the cylinder as projected by their jacks in the manner described by the several cams pertaining thereto. It is therefore unnecessary at this point again to describe 55 the manner in which the needles are thus projected.

We have stated that in the form of the invention illustrated in Figs. 64 and 65, the needles 60 are projected in two series, this being done in two steps or courses. While this is the desired arrangement, it is to be understood that the needles themselves may be otherwise grouped than as alternate needles and that the projection of 65 distributed needles may be done in more than two steps or courses, and that our invention therefore is not limited to the projection being made in two courses. We will, however, describe that embodiment wherein the needles are 70 divided or distributed into two groups or series, the first of which includes alternate needles, and the other of which includes all the remaining needles, and the projection of the needles as so divided or distributed, in two courses 75 or revolutions of the needle cylinder.

In the first course or revolution involving the loading of the transfer points or jacks, the said alternate needles 318 are projected or elevated and all of the transfer points or transfer jacks are projected by the loading cam 204, it being understood 5 that the construction of the dial and its co-acting parts is the same for that form of the invention now described as in the form already described except that only half as many radial grooves are provided for the transfer 10 points or jacks with that form of the invention shown in Figs. 64 and 65 as in that form of the invention previously described. Thus, we are enabled to operate with only half the number of transfer points or jacks and thus can space 15 further circumferentially the radial grooves, thereby providing thicker walls between said grooves. The series of transfer points or jacks employed in this form of the invention is indicated at 319 and the second series of needles is 20 indicated at 320. Having upon the first course or step loaded the loops from one-half the needles, namely, the needles 318, onto the said transfer points or jacks 319, then in another step or course, and desirably upon the next revolution 25 of the needle cylinder, the needles 320,—being all the remaining needles,—are projected or elevated and their loops are loaded onto the transfer points or jacks 319 as the same remain 30 radially projected.

The action in this form of the invention is therefore such as to place each loop only over a single transfer point or jack 319. This is indicated in Figs. 64 and 65 and is more clearly shown in Fig. 74. In the left-hand part of said 35 figure is indicated the loading of the jacks 319 by the loops from the needles 318, and in the right-hand part of said figure is indicated the loading of the same jacks 319 by the loops from the needles 320. Thus it will be evident that 40 each transfer point or jack receives two loops, and it will also be evident that from each transfer point or jack the yarn or thread of the loop passes almost vertically downward to the needle 318 and then, at a much less abrupt upward slope, to the next jack 319. This is clearly shown at the left-hand side of Fig. 74. It will also be evident from the right-hand side of Fig. 74 that in the next course the yarn or thread extends downwardly almost vertically from one 45 of the jacks 319 to the needle 320, and then at a much less abrupt upward slope to the next jack 319, this disposition of the yarn or thread extending throughout the entire circle of needles. Thus between every two transfer points or jacks 50 319 there exist two stretches of yarn or thread lying at slopes which are not abrupt, and here diagrammatically indicated as about 45 degrees. An important advantage of this arrangement is that the web holders between the needles will 55 more surely take over or engage one or both of the oblique stretches of yarn or thread at substantially their crossing points, so as to hold the web down and prevent its riding upward with the needles when the latter rise. This, therefore, is a more advantageous arrangement than exists in that form of the invention first described, as will be shown from a comparison of Figs. 73 and 74. In Fig. 73 is indicated at the 60 right and left hand sides thereof the manner in which the loops in the two courses are laid upon the transfer points or jacks 191 which in such case equal in number the number of the needles. 65

Referring to the left-hand side of said Figure 73, it will be evident that when the alternate 70

needles are projected or elevated, the yarn or thread therefrom is loaded onto the two next adjacent transfer points or jacks, as has been already described. Between each pair of transfer points or jacks and the next pair at either side the yarn or thread extends quite abruptly to the needle as clearly indicated in Fig. 73. At the right-hand side of said figure is shown also the loading of the yarn or thread in the second course, and it will there be observed that each needle loop is laid onto the two next adjacent transfer points or jacks, but in such case the abruptly downwardly extending parts of each loop lie between the downwardly extending loops in the previous course. In this case, therefore, each transfer point or jack also receives two loops or portions thereof.

It will be understood that the means for operating the parts in carrying out that form of our invention indicated in Figs. 64, 65 and 74 is the same as that for carrying out or practising the form of our invention previously described, the only difference being that we employ only one-half as many transfer points or jacks.

Although that form of the invention shown or indicated in Figs. 64, 65 and 74 is the one preferred, we have also indicated certain other forms of our invention in Figs. 66 to 72 and 75 to 78 and will briefly refer thereto.

In Figs. 66, 67 and 75 we have indicated the next form of our invention. In this form we employ as many transfer points as we employ needles, and we project the needles in two series each including alternate needles, in the manner already indicated. We desirably operate in two steps or courses and in the first course, which is indicated in Fig. 66 and also at the left-hand part of Fig. 75, we project or elevate alternate needles 321 and load therefrom the alternate points which are indicated at 322. In another course or step, which desirably is the next succeeding course, we again project the same needles 321,—being the alternate needles throughout the series,—and we load therefrom onto the other transfer points 323. In this case, therefore, only the needles 321 are projected or elevated in the loading operation, the remaining or alternate needles continuing down. However, each and every transfer point receives a single loop, and only a single loop, as is clearly evident from the right-hand side of Fig. 75. At the end of the welt we transfer the loops to the other needles, namely, the remaining or alternate needles which were not projected for the loading operation, and therefore, each of said needles projected for the transferring operation receives two loops, the remaining needles not receiving any loop.

In order to carry out or practise this form of our invention we may employ any means for elevating every other needle, and while we may employ any suitable drive for the dial, we desirably in this form, and all the other forms of our invention, drive the dial from the needles by means of the floating ring hereinbefore described. We may, if desired, for this form of our invention, in the dial employ four lengths of butts on the transfer points or jacks, or we may employ two lengths of butts thereon, and employ swinging loading and transfer cams, such as already described.

In Figs. 68, 69 and 76 we indicate still another form or method of practising our invention. In these figures, which indicate a combination of the first and second forms already described, we, in the first course, or step, project alternate needles and also project only alternate transfer points or

jacks and load the latter. That is to say, in Fig. 68 we indicate the projection or elevation of alternate needles 324, and at the left-hand side of Fig. 76 we have indicated the alternate jacks 325 as projected and the loops received thereon only from the needles 324. Then upon another course or step, and desirably upon the next course, we project the remaining or alternate transfer points 326 and the other needles, namely, the alternate needles 327, and load therefrom the said transfer points or jacks 326. It will be observed that this form of the invention gives the oblique disposition of the lengths of yarn or thread of the loops in both courses, but that these oblique portions in the two courses are parallel with each other instead of crossing each other, as in that form of the invention shown in Fig. 74, and this form of the invention indicated in Figs. 68, 69 and 76 is therefore not so desirable.

Referring to that form of the invention indicated in Fig. 73, it is evident that when the loops are transferred from the points or jacks back to the needles, every needle receives a loop from a transfer point or jack.

In that form of the invention indicated in Fig. 74, which, as stated, is the preferred form of the invention, each and every needle of the entire circular series receives a loop or portion of the yarn or thread when the loops are transferred back to the needles. This is so because of the long loops or sloping portions of the yarn or thread.

In that form of the invention indicated in Fig. 75, wherein in a first course loops are loaded from alternate needles onto alternate transfer points, and in the next course loops are loaded from the same needles onto the remaining transfer points, we, at the end of the welt, transfer from the points or jacks onto the other needles, that is, onto those alternate needles which were not elevated in the loading, such needles being indicated at 328 in Fig. 67. This, therefore, places two loops onto those alternate needles which receive loops at the end of the welt by transfer. Therefore, in this form of our invention we use only every alternate needle while loading, and use only the other needles when transferring, but we employ all the transfer points, namely, as many transfer points as there are needles in the entire circle of needles.

In Figs. 70, 71 and 77 we have indicated still another form of our invention, this being a combination of the preferred form and the third described form. In this case, upon a first course or step, we project or elevate all the needles, but we load therefrom in a first course only alternate points indicated at 329, and in the next course or step we load only the remaining alternate points or jacks 330. This we desirably do in two revolutions. The result of this method of procedure is indicated in Fig. 77, wherein the loops loaded in the first course are represented as received by the transfer points 329, and the loops loaded on the second course are represented as received by the transfer points 330.

In still another form of our invention, which is indicated in Figs. 72 and 78, we use only half as many transfer points 331 as we employ needles, and in this respect the arrangement is similar to that indicated in Figs. 64, 65 and 74. Also we project only alternate needles, namely, those indicated at 332, and this is done in a single step, course or revolution. In other words, in the single step we load from alternate needles 332 onto the alternate transfer points 331, and in so doing we pro-

vide the gentle slope 332^a of the yarn or thread from any one needle to a transfer point that is characteristic of the preferred form of our invention. Therefore, according to this method of loading the loops, the web holders take over or engage the gently sloping part 332^a of the yarn or thread and so prevent the web from rising with the needles.

In said last described form of our invention we also employ the floating ring to be directly engaged by the needles and thereby to rotate the dial.

In Figs. 1, 1^a and 2 we have indicated a stocking and hose made in accordance with our invention. In Fig. 1 the inturned welt of the stocking is indicated at 333, the leg thereof at 334, the upper part of the foot at 335, the high splice at 336, the heel at 337, the bottom of the foot at 338 and the toe at 339. It will be evident from the foregoing description that a portion of the ankle and the high splice as well as the foot are made by split work, and we have indicated one of the suture lines in the high splice at 340 and in the foot at 341. The same construction is indicated in the hose represented in Fig. 2, and the same reference characters are therefore there employed.

In Fig. 1^a we have diagrammatically indicated a portion of a string of stockings. In such case the leg of each stocking is indicated at 334, the heel at 337 and the toe at 339.

In Figs. 1 and 2 we have indicated the toe seam at 342 as it appears on the stocking or hose as completed; but it will be understood that in actual practise, according to the preferred form or method of practising our invention, we employ a breaking thread which desirably will be thrown in just after the loop-around course or courses, or as such course or courses, and we have indicated the breaking thread as constituting one or more courses at 343 at two points in Fig. 1^a.

In Fig. 3 we have indicated somewhat diagrammatically the structure of the courses in the formation of the welt, including a few courses preliminary thereto and a few of the courses of plain work following the completion of the welt.

In said figure we have indicated at 344 and 345 two courses which are formed of a breaking thread and which, as stated, may constitute the loop-around courses or some of them. Immediately following said two courses we form a course 346 which is an anti-ravel course and is shown as knitted only upon alternate needles. Then we form a plain course 347 which, as shown, is formed upon every needle. Then we form a course 348 which is one of the courses in which we load the yarn onto the transfer points, as already described. Then we form another course 349, which is the second course during which loading of the transfer points or jacks occurs, as already described. The loops of the first of said loading courses 348 are indicated at 350, and it will be observed that they are here shown as relatively long loops. The loops of the other loading course 349 are indicated at 351 and it will be evident that they are shown as somewhat shorter loops because the two sets of loops are loaded in different courses, but the illustration is more or less diagrammatic in this respect for sake of clearness. Following the formation of the second loading course 349, we form the welt indicated as an indefinite number of courses 352, and finally we transfer all the loops back from the transfer points or jacks onto the needles or 75 onto selected needles, as the case may be. This

course is indicated at 353 and thereafter the knitting of the leg is proceeded with as indicated by the indefinite number of courses 354.

We have stated that we employ yarn holding and yarn cutting means for the secondary yarn 5 and also for the main yarn and to that end utilize the dial cam plate as a convenient support therefor.

Reference is made more particularly to Figs. 13, 14, 58 to 61, as well as to Figs. 4, 5 and 21, for 10 showing the operating connections.

The hub 196 shown as integral with the dial cap 195 is itself shaped, as by providing integral enlargements or vertical surfaces, to have secured thereto suitable means for cutting and 15 clamping both the primary yarn and the secondary yarn. These means, so far as the primary yarn is concerned, may be and desirably are similar to those disclosed in the patent to Joshua B. Hemphill, No. 933,443, the dial cap being 20 merely utilized as a convenient support in lieu of the plate which in the machine shown in said Hemphill patent is located within the needle circle at substantially the same position in space 25 as the dial or dial cap.

Upon the web 184 is provided a suitable boss 355 whereon is pivoted by screw 356 a lever 357 whereof the arm 358 extends outwardly and by its end 359 is connected to any suitable operating means and as shown most clearly in Fig. 5 30 to a downwardly extending rod or link 360. At its lower end said rod is connected to lever 361 Fig. 29 pivoted at 362 constituting also the pivot for lever 113, and which lever 113 at its opposite end is pivotally connected at 363 to link 115. The 35 said link 115 is pivotally connected at 364 as clearly shown in Fig. 21, to a lever 365 whose arm 366 rides upon the cam surface 116 of the cam 19, shown most clearly in Fig. 4. Preferably we provide a coil spring 367 surrounding the rod 40 360 between brackets 368 and 369, said spring tending to move the rod 360 downward and thereby to open the cutters.

Referring again to Figs. 13, 14 and 58 to 61, it will be noted that the lever 357 is provided with 45 a second arm 370 pivotally connected at 371 to a link 372 itself pivotally connected at 373 to a lever 374 pivoted at 375 upon a slight enlargement of the hub 196. The forward edge 376 of said lever 374 constitutes a cutting edge, being 50 shown most clearly in Fig. 59 and cooperates with a similar cutting edge 377 upon a suitable metal piece secured to a slight enlargement of the hub 196.

The binder lever 378 for the primary yarn, as 55 indicated most clearly in Figs. 58, 59 and 60, is located at the opposite side of the dial hub 156 from the primary yarn cutter. The said binder is pivoted at 379 upon an enlargement of the dial hub 156 and about its pivot is provided a 60 coil spring 380 tending to close the binder directly against the top surface of a dial cap. Fixedly secured in the outer end of the binder lever 378 is a horizontally extending bolt 381 which takes over and rests upon the cutter lever 374 and is 65 moved thereby when the cutter is opened through the connections for the cam 19. Thus when the cutter for the primary yarn is opened the binder is also opened.

It will be understood from the foregoing description that the dial cap merely serves as a 70 convenient support, taking the position in space of the previously employed plate within the needle circle.

To sever and bind the secondary yarn we 75

provide any suitable yarn severing and clamping means suitably located with respect to the auxiliary yarn guide. We have here shown said auxiliary yarn cutter and binder as located about 5 90° circumferentially from the pivots of the primary yarn cutter and binder respectively. As shown in Fig. 13, the lever arm 370 is connected at 382 to a vertically positioned member 383 mounted for slight vertical movement upon an 10 enlargement 384 of the hub 195. Said member 383 is provided in one edge near its lower end with the cutting notch 385 that in the movement of said member 383 moves past the cutting and clamping edges respectively of two plates 386 15 and 387 so that in the vertical movements of said member 383 the secondary or auxiliary yarn is severed and the free end is clamped and held for reentry to the needles. Desirably the top surface of the dial cap 195 is slightly thickened as 20 indicated at 388 in Fig. 58 to provide a guiding surface 389 to direct the yarn into the cutter and to provide a slight notch or recess 390 into which the cutter member 383 moves.

It will be noted that the top surface of the 25 dial cap 195 is smooth excepting for the slight enlargement 388 and that it functions merely as the usual plate provided within the needle circle as disclosed in Hemphill Patent No. 933,443 and other patents.

30 We have stated that in accordance with the preferred embodiment of the invention the stockings are connected with each other by a breaking yarn, thus forming a continuous string. We may in certain cases, however, automatically cause 35 the web holders to cease functioning at the conclusion of the looper-round so that each stocking is dropped from the needles as finished and the next stocking is begun by introducing the yarn to the bare needles in a manner long customary in the art.

In Figs. 79 to 84 we have illustrated one means for accomplishing this result.

Therein the sinker head is indicated at 57 and the sinker cam ring is indicated at 58. Both 45 of these are constructed and operate as in the well-known Banner machine excepting as now to be described. The sinker cam ring 58 is provided with a circumferentially extending groove 390 of a proper length to receive a lip or projecting edge 391 that extends laterally from a segment 392, the latter being thus guided for periodic movement in a circumferential direction. Said segment has connected thereto at 393 a coil spring 394 which is at its other end connected 50 at 395 to the sinker cam ring 58.

Upon a suitable bracket upstanding from the framing at the auxiliary side of the machine is pivoted at 396 a lever 397 shown as broken off at its outer end. It is, however, adapted at about 60 the termination of each stocking to be rocked slightly in an upward direction in any manner, whether manually or otherwise, thereby bringing a block 398 fast thereon into engagement with a plate 399. Said plate 399 is loosely pivoted as indicated in Fig. 83 upon a bolt or screw 400 which has surrounding it a coil spring 401 tending to hold said plate upward in a horizontal position. The upper surface of the block 398 is tapered 65 or wedge shaped, as shown most clearly in Fig. 84, so that in the contraclockwise movement of the needle cylinder and parts moving therewith the said block 398 will tilt the plate 399 so as to withdraw its inner edge from a notch 402 in 70 the sinker cam ring 58, thereby permitting the

spring 394 to function and draw the segment 392 in a clockwise direction.

The result of such movement of the segment 392 is to cause the pin 403 upstanding from said segment to move in the inclined slot 404 of the block 405 and thus to move the said block radially outward. The said block 405 is connected by a stem 406 to a usual cam 407 acting upon the sinkers or web holders, and when said cam is withdrawn the sinkers or web holders cease to 10 function in the formation of stitches and permit the fabric to drop from the needles at the termination of the toe of the stocking or the looper-round following the same.

When the next stocking is begun, the slight 15 return movement of the segment 392 through action of coil spring 394, causes the plate 399 to come against the bevel shoulder 408 which thereby causes said plate to snap into the notch 402 so that the segment is held in place until the completion of the next stocking.

Desirably we use a latch opener which is or may be in operation at all times so as to function to open the needle latches. In the disclosed embodiment of the invention, the latch opener, 25 which is shown most clearly at 409 in Figs. 8 and 9, has opposite tapering sides or faces, a straight upper edge 410 and a sloping lower edge 411. Thus, the two lateral faces of the latch opener taper toward each other and the lower edge or 30 face 411 slopes upwardly to the point 412. As shown most clearly in Fig. 9, the latch opener is of a general bow shape having an end 413 in which is received a rod or stem 414 threaded as indicated at 415 for the reception of adjusting 35 and lock nuts 416, whereby the latch opener may be adjusted lengthwise in its support. Said support consists of a long vertically positioned sleeve 417 which is supported for rotative adjustment upon a stud 418 rising from the bed plate. A 40 screw 419 is provided to secure the sleeve 417 in desired position of rotative adjustment.

We provide means acting normally to hold the latch opener yieldingly in functioning position. For that purpose we have, as shown most clearly 45 in Fig. 11, provided a member 420 extending about and secured to the sleeve 417 and provided with a set screw 421 held by coil spring 422 against some suitable part of the machine and herein the housing or guide for the instep cams.

We have described the means for moving the loading cam 204 for the transfer points or jacks outwardly into loading position. The primary control for such loading cam is, as previously stated, the disk portion 219 of the auxiliary drum 55 shown in Fig. 25, and which acts through control of the lever 256 and intermediate connections to move the loading cam 204 outwardly into loading position.

Desirably, but not necessarily, we provide 60 means further and accurately to control the period during which said loading cam 204 shall be in its loading position. We have stated that the transfer points or jacks are in loading position during two courses. In order accurately to 65 keep them in their loading position during such two courses, we preferably provide upon the usual so-called "104" gear 423, shown most clearly in Fig. 5, a cam 424 which is of such length as to exercise its control during two courses upon the 70 connections for operating the loading cam. Said "104" gear makes one revolution to four revolutions of the needle cylinder. Hence said cam 424 extends throughout 180° of said "104" gear. Said cam 424 acts upon the roll 425 upon lever 75

arm 426 mounted upon the stud 246 and is fast with the connections for the loading cam, so that as the loading cam is thrown inwardly the roll 425 is moved downwardly into the path of the said cam 424, and therefore the latter accurately maintains the loading cam and the transfer points or jacks in loading position during two courses.

We may, if desired, and as shown in this embodiment of the invention, employ locking or like means which prevents the movement of the loading cam into its outward position until the proper time. For this purpose, we provide, as shown most clearly in Fig. 8, a downward extension 427 fast or integral with the lever 264 constituting a part of the connections for the loading cam. Said lever 427 is shouldered at its lower end as indicated at 428 and therewith engages the upper end 429 of a vertically extending rod 430 shown most completely in Fig. 5. Said rod 430 is connected at its lower end as indicated at 431 to the outer end of the lever 237 as indicated in Fig. 21. As previously stated, the lever 237 controls the movement of cam 140. Thus when the cam 140 is moved inward for position No. 4, the lock 429 is removed and the loading cam 204 is permitted to be moved into its outward or loading position as a part of the movement for position No. 4.

We have referred to the extra movement of the instep cams 27, 28. This so-called extra movement is a movement into an intermediate position and occurs at the end of the second course in position No. 5, so that such intermediate position exists for general position No. 6, as indicated in Fig. 46. This extra movement of the instep cams 27, 28 is provided so as to throw the long butt needles over cam 140, thus allowing cam 140 to be withdrawn. This intermediate position of the instep cams 27, 28 is a brief one.

We have previously stated that we desirably throw in an extra thread during the loading of the transfer points or jacks so as to prevent the cutting of the main thread when the latter is lying across the transfer jacks. That is to say, we provide an additional thread so that the main thread and the additional thread are loaded together onto transfer jacks.

For this purpose, and as shown most clearly in Figs. 6, 7, 9, 11, 12 and 21, we provide the lever 237 which controls the cam 140, as shown most clearly in Fig. 21, with an extra link connection 432, which, as indicated in Fig. 6, extends upwardly and at its upper end is pivotally connected at 433 to the end of a lever 434, shown most clearly in Fig. 11 as pivoted at 435 and having a free end 436, which, as indicated most clearly in Fig. 7, is maintained at all times when the extra yarn is not to be thrown in, in elevated position at the under side of the yarn controlling lever 437, which as there shown acts to hold the yarn guide 438 out of feeding position or to permit it to drop or descend into feeding position. The downward movement of the end 436 of the lever 434, which takes place at the proper time through the described connections, permits the said extra yarn guide 438 to move into feeding position.

Desirably and as shown in Figs. 14 and 61, we provide the collar 196^a with ball bearings 439 cooperating with the ball bearings 199 to permit the free and ready rotation of the dial and its stud 186 by and with the needles.

Except as otherwise indicated in certain of the diagrams, we have indicated the needles at 440.

Throughout our description of diagrammatic Figs. 64 to 78, we refer to the needles as pro-

jected or elevated. We thereby indicated that the needles referred to have been projected or elevated, so that the transfer points in question receive loops therefrom, and thereupon the said needles have been lowered. Therefore, when we refer to said diagrams as indicating the projections or elevations of certain needles, we mean those needles the loops from which extend to the transfer points, and thereupon such needles have been lowered and are shown as lowered.

From the foregoing description, it will be apparent that we have provided a novel organization of cooperating parts whereby the welt, and especially an inturned welt, may be formed upon split work hosiery. Because of the fact that in the formation of split work hosiery float threads are avoided, we are enabled so to co-relate the yarn feeding, driving and other features of the dial as to provide mechanism accomplishing a wholly novel result. So far as we are aware no one has heretofore actually constructed or placed upon the market split work hosiery having an integral welt, nor so far as we are aware has anyone heretofore appreciated the fact that because of the absence of float threads in split work the dial for the welt can be advantageously driven from the needles themselves instead of through gearing. Certain features of our invention, and particularly of the float ring, may obviously be employed in other relations than in the formation of welts upon hosiery, and the several functions of the float ring may be utilized each independently of the other and in other combinations than herein disclosed or referred to.

In the formation of a welt upon a machine having an auxiliary cam feed, it is important that the auxiliary block carrying the auxiliary knitting cam set be raised to such a height in taking on the threads for the welt that the stitches are not pulled down so low as to break the stitches, and it is then important to lower the said block for one or two courses after the taking on or loading for the welt. This also cooperates in keeping the work under the web holders so that the same will not rise with the needles. Preferably in transferring the loops back to the needles the auxiliary block is lowered to its normal knitting position.

It is found preferable to bring back or start to bring back the transfer points or jacks before the knitting point is reached at the regular knitting side which is the side where the loading is effected.

Having thus described certain illustrative embodiments of the mechanism of our invention and the best methods known to us for practicing the same, and having described one embodiment of the fabric of our invention, we desire it to be understood that although specific terms are employed, they are used in a generic and descriptive sense and not for purposes of limitation, the scope of the invention being set forth in the following claims.

We claim:—

1. In the process of forming a welt integral with the leg portion of circular knit hosiery upon a circular series of needles; loading the thread on transfer instruments in a series of steps, each step involving a distinct relative rotation of the needle carrier with respect to the operating cams, whereby some of said instruments receive the thread in the first step and others receive the thread in a subsequent step.

2. In the process of forming a welt integral with the leg portion of hosiery; laying or loading the thread on transfer instruments in a series of

- courses, whereby some of said instruments receive or are loaded with the thread in a first course, and others receive or are loaded with the thread in a subsequent course.
- 5 3. In the process of forming a welt integral with the leg portion of hosiery; loading alternate transfer instruments on a first course and loading the remaining instruments on a subsequent course.
- 10 4. In the process of forming a welt integral with the leg portion of hosiery; loading alternate transfer instruments on a first course and loading the remaining instruments on the next course.
- 15 5. That process of loading the loops for welt formation onto substantially an entire circular series of transfer points which consists in loading materially less than all the instruments in one course and loading the remainder in a successive course.
- 20 6. A transfer instrument for use in a welt knitting machine having a hook for the loading thereon of a loop from the needle, said instrument being of the same lateral thickness throughout except that part whereon the loop is laid or received, such part being laterally thicker than said hook.
7. In a circular plain knitting machine having a needle cylinder with needles, a welting dial having an element driven by direct engagement with the cylinder needles.
8. In a circular plain knitting machine having a rotatable needle cylinder, a welting dial having an element driven by the needles in said cylinder.
- 35 9. In a circular plain knitting machine having a rotatable needle cylinder, a dial for supporting transfer points to receive loops from the needles, such dial having at least a portion thereof driven by the needles in said cylinder.
- 40 10. In a circular plain knitting machine for knitting hosiery having an integral welt, said machine having a needle cylinder with needles, an upright supporting post, a bracket mounted for turning movement thereon, a dial stud revolvably supported by said bracket and a dial rotatable with said stud, said dial having an element rotated by the cylinder needles.
- 50 11. In a circular knitting machine, an upright supporting post, a bracket mounted for turning movement thereon, a dial stud revolvably supported by said bracket and a dial rotatable with said stud, said dial having a floating ring engaging the needles and driven thereby and thereby causing rotation of the dial.
- 55 12. In a circular knitting machine, an upright supporting post, a bracket mounted for turning movement thereon, a dial stud revolvably supported by said bracket and a dial rotatable with said stud, transfer instruments mounted in said dial, and a floating ring directly engaging the needles and rotated thereby, so as through said transfer instruments to cause rotation of the dial.
- 60 13. In a circular welt knitting machine having a needle cylinder and needles therein, a dial, means to support the same within the cylinder needles and having a part rotated by the said needles, a dial cap, and means to hold the dial cap from rotation.
- 65 14. In a circular welt knitting machine having a needle cylinder and needles therein, a dial, means to support the same within the cylinder needles and having a part rotated by the said needles, a dial cap and means to hold the dial cap from rotation, together with means readily to release said dial cap from its non-rotative position.
- 15 15. In a circular knitting machine having a needle cylinder and needles therein, a dial, means to support the same within the cylinder needles and having a part rotated by the said needles, an upright stud supporting the dial and having a threaded portion, a dial cap, and means engaging said threaded portion to prevent rotation of the dial cap. 5
16. In a circular knitting machine having a needle cylinder and needles therein, a ring positionable within the cylinder needles and driven wholly by the said needles.
17. In a circular knitting machine having a needle cylinder and needles therein, a ring positionable within the cylinder needles and having groove-like formations co-related to the needles to true the said needles. 15
18. In a circular knitting machine having a needle cylinder and needles therein, a ring positionable within the cylinder needles and directly engaging the said needles and having groove-like formations co-related to the needles to true the same. 20
19. In a circular knitting machine having a needle cylinder and needles therein, a dial positionable operatively with respect to the cylinder needles and having in and out movable instrumentalities, and a floating ring cooperating with said dial and having capacity to true said instrumentalities. 30
20. In a circular knitting machine having a needle cylinder and needles therein, a welting dial positionable operatively with respect to the cylinder needles and having in and out movable welting instrumentalities, and a ring cooperating with said dial and driven by the said needles and having capacity to drive the dial. 35
21. In a circular knitting machine having a needle cylinder and needles therein, a dial having transfer instruments movable in and out, and a floating ring overlying said instruments and driven by direct engagement with the said needles and acting to drive the dial through said transfer instruments. 40
22. In a circular knitting machine having a needle cylinder and needles therein, a floating ring having its outer edge toothed in co-relation to the needles for direct engagement with the said needles. 50
23. In a circular welting knitting machine having a needle cylinder and needles therein, a floating ring forming an element of a welting dial structure and having grooves for the reception of welting instrumentalities carried by and movable with respect to said dial structure. 55
24. In a circular knitting machine having a needle cylinder and needles therein, a dial structure having a floating ring, one face of which is grooved for the reception of movable instrumentalities and the outer edge whereof is toothed in co-relation with and for engagement with the said needles. 60
25. In a circular welting knitting machine having a needle cylinder and needles therein, a welting dial structure including a dial having in and out movable welting instrumentalities, a dial cap and an intermediate floating ring adapted for direct engagement both with said instrumentalities and with the said needles. 65
26. For the purpose of presenting the needles thereof in distributed groups to the action of transfer instruments for cooperating in making a welt integral with hosiery, a circular knitting ma- 70
- 75

- chine having long and short butt needles, long and short jacks under the needles, the jacks under the long butt needles having long butts and those under the short butt needles having short butts, a distributed group of said jacks being long and a distributed group of said jacks being short, a dial with transfer instruments adapted to cooperate with said needles in the formation of a welt whereby the needles are selectively presented in accordance with the distinctive formation of the jacks thereunder to the transfer instruments of the dial in the formation of a welt, said jacks acting according to their formations to present the needles to the transfer points.
27. A circular knitting machine having a circular series of latch needles, a latch ring pivoted to be swung into and out of functioning position, and a dial mounted to be positioned within the needle circle and supported wholly independently of said latch ring and adapted to be moved independently thereof into and out of functioning position.
28. In a circular knitting machine, a circular series of needles, a curved yarn guide-supporting member mounted upon a horizontal pivot for movement into and out of functioning position with respect to said needles, and a dial mounted independently of said member, upon a vertical pivot, for lateral movement into and out of functioning position with respect to said needles.
29. In a circular welting knitting machine having a needle cylinder with needles, a welting dial having welting instrumentalities driven by direct engagement of a part thereof with the cylinder needles.
30. In a circular welting knitting machine having a needle cylinder with needles, a welting dial having welting instrumentalities and having a part thereof directly engaging the backs of the cylinder needles below the hooks thereof whereby driving of the dial is effected.
31. A circular split work welting knitting machine, comprising a needle cylinder with needles, main and auxiliary sets of knitting cams, yarn guides respectively cooperating therewith for the formation of split work, and a dial positionable within the cylinder needles for the formation of the welt, and driven by direct engagement of a part thereof with the cylinder needles.
32. In the process of loading a series of transfer instrumentalities, loading selected distributed instrumentalities of said series during a first revolution of the needle carrier with respect to the operating cams and upon a subsequent revolution loading other distributed instrumentalities of said series than those loaded upon the first specified revolution.
33. In the process of loading a series of transfer instrumentalities for welt formation, loading distributed instrumentalities of said series less than the whole number during a revolution, and on a subsequent revolution loading other distributed instrumentalities of said series.
34. In a circular knitting machine, a circular series of needles, knitting cams therefor, an instep cam, means to impart normal movement to the instep cam for heel and toe formation, a dial and cooperating means for forming a welt, and cam means to control the presentation of the needles to the transfer instruments for welt formation, and including means to impart an additional movement to said instep cam.
35. In a circular welting knitting machine, a dial having a part rotated by the needles, transfer instruments movable in said dial and load-
- ing and transfer cams for said instruments, said cams being mounted for radial movement only, and confined from vertical movement.
36. In a circular welting latch needle knitting machine, a latch ring mounted to be swung up and down from and to operative positions, a dial supported within the circle of needles with capacity for lateral swinging movement into and out of functioning position, and means for adjusting said dial into accurately concentric relation with respect to the needle circle.
37. In the process of forming a welt integral with the leg portion of hosiery; providing a series of transfer instruments corresponding in number to one-half the number of needles; loading in one course a loop from each of alternate needles onto each of said transfer instruments, and in another course loading a loop from each of the remaining needles onto each of said transfer instruments.
38. In the process of forming a welt integral with the leg portion of hosiery; providing a series of transfer instruments corresponding in number to one-half the number of needles; loading in one course a loop from each of a predetermined number of needles less than the entire number of needles, and in another course loading from each of other predetermined needles onto each of said transfer instruments.
39. In the process of forming a welt integral with the leg portion of hosiery; loading alternate transfer instruments on a first course and loading the remaining instruments on a subsequent course, knitting the welt portion and transferring substantially all the loops in a course back to selected needles.
40. That process of forming a welt upon a seamless stocking including the following steps: (a) forming an anti-ravel course; (b) causing every needle to knit; (c) projecting a distributed group of needles and projecting the transfer instruments so instruments may receive loops; (d) projecting another distributed group of needles so that the instruments may receive loops; (e) retracting all the transfer instruments while holding their loops; (f) forming plain knitting to make the desired length of welt; and (g) projecting all said transfer instruments so that all the needles may receive their loops therefrom.
41. That process of forming a welt upon a seamless stocking including the following steps: (a) forming an anti-ravel course by knitting upon alternate needles; (b) knitting upon every needle; (c) projecting a distributed group of the needles and also projecting the transfer instruments so that instruments may receive loops; (d) feeding an extra yarn to prevent yarn breakage; (e) projecting another distributed group of needles so that instruments may receive loops; (f) retracting all the transfer instruments while holding their loops; (g) forming plain knitting to make the desired length of welt; and (h) projecting all the transfer instruments so that all the needles may receive loops therefrom.
42. In the process of knitting a stocking having an integral welt upon a series of needles of a circular knitting machine, providing a circular series of transfer instruments substantially equal in number to one-half the number of needles in said series, loading in one course all of said transfer instruments with loops from alternate needles of the series of needles, and loading in another course all of said transfer instruments with loops from the remaining needles of the series of needles.

43. In the process of knitting a stocking having an integral welt upon a series of needles of a circular knitting machine, providing a circular series of transfer instruments substantially equal 5 in number to one-half the number of needles in said series, loading in one course all of said transfer instruments with loops from alternate needles of the series of needles, loading in another course all of said transfer instruments with loops from 10 the remaining needles of the series of needles, whereby the parts of the loops in said two courses cross each other, and causing the web holders to engage parts of said loops, thereby to hold down the work upon projection of the needles.
44. A circular welt knitting machine having a circular series of needles, a circular series of transfer instruments in number substantially equal to one-half the number of needles, and means acting in one course to load loops from 15 alternate needles of said series onto all of said transfer instruments and acting in another course to load loops from the remaining needles onto all of said transfer instruments. 20
45. A circular welt knitting machine having a circular series of needles, a circular series of transfer instruments in number substantially equal to one-half the number of needles, means acting in one course to load loops from alternate 5 needles of said series onto all of said transfer instruments and acting in another course to load loops from the remaining needles onto all of said transfer instruments, and subsequently acting means to transfer all of said loops to needles 10 of said circular series of needles.
46. In the process of knitting a stocking having an integral welt upon a circular series of needles of a circular knitting machine, providing a circular series of transfer instruments equaling in 15 number one-half the number of the needles of said circular series, projecting alternate needles of said series in each of two different revolutions, and loading the loops therefrom one onto each of said transfer instruments. 20
